AUTOMATIC ALIGNMENT SYSTEM

Kurt Enslein, Rochester, N. Y., assignor, by mesne assignments, to General Dynamics Corporation, a corporation of Delaware

Application February 5, 1951, Serial No. 209,357

33 Claims. (Cl. 250—40)

The present invention relates to an alignment system for automatically aligning electrical circuits, and, more particularly, to an improved system for accurately and quickly tuning resonant circuits to a predetermined frequency. Specifically, the present invention is an improvement on the automatic alignment method and apparatus disclosed and claimed in applicant's copending application, Serial No. 157,160 filed on April 20, 1950, now Patent 2,584,004, and assigned to the same assignee as the present invention.

In many instances, it is necessary to align an electrical circuit to a predetermined frequency. For example, each of the radio and television receivers which are now being produced in great volume include a number of resonant circuits which must be tuned to the correct operating frequencies. Up to the present time, the alignment of such resonant circuits is performed manually by trained operators. Each operator views the response of each resonant circuit on an oscilloscope, or on an indicating meter, and manually tunes the resonant circuit to the correct frequency as indicated by a maximum or peak response of the resonant circuit. Such an alignment procedure is inherently laborious and time consuming and requires skilled personnel to manipulate the test equipment and interpret the data obtained. While a human operator can align a single resonant circuit with good accuracy and in a relatively short period of time, when he attempts to align resonant circuits one after the other, he is unable to operate with any acceptable speed or accuracy over long periods of time. Consequently, when tunable circuits are aligned manually, the results are unreliable and are very non-uniform. In some instances, the resonant circuits, when manually tuned, may be as much as 30% off in amplitude from the desired peak response point, which results in an inferior receiver and in non-uniformity in the receivers produced. It is, therefore, desirable to have a fully automatic alignment system wherein resonant circuits can be accurately, reliably and uniformly aligned to the correct operating frequencies. Also, it is desirable to decrease the time required to tune each circuit to the correct operating frequency without employing highly skilled technicians so that more receivers can be tuned in a given period of time and the expense of operating personnel can be reduced.

It is, accordingly, an object of the present invention to provide a new and improved apparatus for automatically aligning electrical circuits to predetermined frequencies.

It is another object of the present invention to provide a new and improved apparatus for automatically tuning resonant circuits to predetermined frequencies which is particularly suitable for use by unskilled operators on a production line basis.

It is a further object of the present invention to provide a new and improved apparatus for automatically aligning electrical circuits to predetermined frequencies which is particularly suitable for use by unskilled operators and wherein alignment may be accomplished with a high degree of accuracy.

2

It is a still further object of the present invention to provide a new and improved apparatus for automatically aligning electrical circuits to predetermined frequencies wherein such alignment may be accomplished by unskilled operators in a minimum amount of time on a production line basis and with a high degree of uniformity of the aligned circuits.

The invention, both as to its organization and method of operation, together with further objects and advantages 10 thereof, will best be understood by reference to the following specification taken in connection with the accompanying drawings, in which:

Fig. 1 is a schematic diagram in block diagram form of an automatic alignment system embodying the present 15 invention;

Figs. 2(a)–2(c) inclusive, 8(a), 8(b) and 9(a)–9(d) inclusive are timing diagrams illustrating the operation of certain portions of the system of Fig. 1;

Figs. 3–7 inclusive and Figs. 10–15 inclusive are detailed schematic diagrams of portions of the automatic alignment system of Fig. 1;

Fig. 16 is a schematic diagram in block diagram form of an alternative alignment system embodying the present 20 invention;

Fig. 17 is a detailed schematic diagram of a portion of the system of Fig. 16;

Fig. 18 is a schematic diagram in block diagram form of a further alternative alignment system embodying the 25 present invention; and

Figs. 19 to 26 inclusive are detailed schematic diagrams of portions of the system of Fig. 18.

Referring now to the drawings and more particularly to Fig. 1 thereof, there is illustrated in block diagram form one alignment system embodying the present invention which is capable of accurately aligning resonant circuits to a predetermined frequency on a fully automatic basis and with very much less time expended than with manual alignment. The automatic alignment system is shown in connection with a modulated carrier wave receiver, indicated generally at 10 which contains a plurality of resonant circuits which are to be aligned to a predetermined frequency, one of which circuits is illustrated at 15, and comprises an inductance coil 16 and a condenser 17. A fixed frequency alignment signal generator 11 is connected to the receiver 10 over the conductor 11a and supplies an alignment signal to the resonant circuit 15 at the frequency to which the circuit 15 is to be tuned.

While the resonant circuit 15 may be energized by any 50 suitable means from the preceding stage in the receiver, in the illustrated embodiment the inductance 16 is shown as the secondary winding of an interstage transformer 22, the primary of transformer 22 being connected to the anode of the preceding amplifier tube 23. The resonant frequency, or tuning, of the resonant circuit 15 is varied by any suitable means such as the tuning slug 24 which is movable within the coil 16 of the resonant circuit to change the inductance thereof and tune the circuit 15 continuously through a band of frequencies which includes the predetermined frequency with which the circuit 15 is to be aligned. Movement of the tuning slug is done under the control of a reversible driving motor 25 which drives a suitable tool 26, such as a screw driver or the like, which engages the tuning slug 24. The tool 26 may be engaged with the tuning slug 24 either manually by the operator or by means of automatic or semi-automatic positioning apparatus. The speed and direction of rotation of the motor 25 are controlled by the alignment system of the present invention, as will be described in more detail hereinafter. 55 60 65 70

When a fixed frequency signal is supplied to the resonant circuit 15 in the manner described above the resonant frequency of the circuit 15 is varied by moving the tuning

slug 24 in a predetermined direction, the signal produced across the resonant circuit will vary in accordance with the well known resonance phenomenon and will be a maximum when the resonant frequency of the circuit 15 corresponds exactly to the frequency of the alignment signal, or, in other words, when the circuit 15 is at peak resonance. The signal thus produced across the resonant circuit 15 is detected in the detector circuit including the rectifier 18, the load resistor 19 and the filter condenser 21, to provide a unidirectional voltage which is proportional to the instantaneous response of the resonant circuit 15, the detector output voltage being used as an input signal for the alignment system proper.

Generally considered, the automatic alignment apparatus of Fig. 1 aligns the circuit 15 with the frequency of the signal generator 11 by first moving the tuning slug 24 past the maximum or peak resonance point of the circuit 15 to establish a sustained reference voltage which is proportional to the response of the circuit 15 at the desired peak resonance point. After the peak resonance point is passed and the reference voltage has been established, the direction of movement of the tuning slug 24 is reversed and tuning of the circuit 15 is controlled in accordance with the difference between the reference voltage and the instantaneous voltage across the circuit 15 so that the circuit is tuned back to its peak resonance point. When the reference voltage and the instantaneous response of the circuit 15 agree, the circuit 15 is tuned correctly and movement of the tuning slug is halted. Inasmuch as the reference voltage once established must be maintained substantially without change during the alignment cycle it may be called a memory voltage and this voltage will be thus referred to hereinafter.

To accomplish the above-described alignment operations the automatic alignment system comprises a memory system which in general performs the function of establishing the memory voltage which is proportional to the peak response of the circuit 15 and a motor control system which in general performs the function of controlling the speed and direction of rotation of the motor 25 so as to tune the circuit 15 in the manner described above.

The memory system includes a comparison bridge 30, a chopping circuit 31, a gating amplifier 36, a switching circuit 37, and a memory circuit 38. The memory circuit 38 includes a storage element in the form of a memory storage condenser having a very high leakage resistance so that the condenser once charged will not lose any appreciable charge for the remainder of the alignment cycle. Charging of the memory condenser is controlled by the instantaneous resonant circuit voltage so that the voltage across the memory condenser follows the resonant circuit voltage up to the peak response point and thereafter remains at peak voltage to provide the sustained memory signal described above.

The comparison bridge 30 performs the function of comparing the instantaneous response voltage of the circuit 15 with the voltage across the memory condenser of the circuit 38 to provide an error output signal equal to the difference between these voltages. To perform this function the comparison bridge 30 is supplied with an input signal from the detector load circuit 19 and 21 over the conductor 12 and with memory voltage from the memory circuit 38 over the conductor 14.

The chopping circuit 31 performs the function of converting the error output signal from the comparison bridge 30 into a square wave of proportionate amplitude and sense. Thus, when the resonant circuit voltage is greater than the memory circuit voltage, the square wave produced by the chopping circuit 31 is of a given polarity and has an amplitude proportional to the difference between these voltages. When the resonant circuit voltage is less than the memory circuit voltage the square wave produced by the chopping circuit 31 is of the opposite polarity and has an amplitude proportional to the difference between these voltages. To perform the above described function

the chopping circuit 31 receives the output of the comparison bridge 30 over the conductor 13 and is controlled by a standard oscillator 39 which supplies a control voltage to the chopping circuit 31 over the conductor 29 to control the generation of the above-described square wave.

The square wave produced by the chopping circuit 31 is supplied to the gating amplifier 36 over the conductor 26a and the unit 36 performs the function of passing only square waves of one polarity. Specifically, the gating amplifier 36 passes only a square wave of the polarity which is produced when the instantaneous resonant circuit voltage is greater than the memory condenser voltage. To perform this function the gating amplifier 36 is controlled by a square wave generator 41 which latter unit supplies a square wave of positive polarity to the gating amplifier over the conductor 40 and is itself controlled by the standard oscillator 39.

The switching circuit 37 in general performs the function of controlling the intervals during which the memory storage condenser of the memory circuit 38 is charged from an independent voltage source. To perform this function the switching circuit 37 is turned on under the control of the gating amplifier 36 which supplies a keying pulse to the unit 37 over the conductor 27 to initiate charging of the memory storage condenser. The switching circuit may be turned off by either one of two different systems to effect either a sequential or a coincidence type of charging of this condenser. In the sequential system of charging the memory condenser the condenser is charged by definite increments until the memory condenser voltage is equal to the detector voltage at which time the charging intervals cease. In the coincidence system of charging the memory condenser the condenser is continuously charged, once the charging circuit is turned on, until the memory condenser voltage coincides with the detector voltage at which time a coincidence signal is derived which is used to turn off the switching circuit 37 and halt charging of the memory condenser. In the system illustrated in Fig. 1 the switching circuit 37 is so connected as to effect a sequential type of charging of the memory storage condenser. More specifically, the switching circuit 37 is turned off under the control of a positive square wave supplied from the square wave generator 41 over the conductor 40. A coincidence system of charging the memory condenser is shown in Fig. 16 and will be described in more detail in connection therewith.

In order to control the driving motor 25 in a manner to tune the circuit 15 initially through the peak response point and thereafter tune the circuit 15 back to the peak response point under the control of the memorized reference voltage produced in the manner described above by the memory circuit 38, there is provided the motor control system which includes the comparison bridge 30, the chopping circuit 31, an A. C. amplifier 32, a balanced keyed rectifier circuit 33, a differential D. C. amplifier 34, a differential relay 35, a starting circuit 42, a reversing counter circuit 45, a reversing relay circuit 43 and a motor driving circuit 44.

The starting circuit 42 includes the starting switch 500 which, upon closure, initiates the alignment cycle and performs the functions of supplying an independent control voltage at the start of the alignment cycle to cause the motor 25 to tune the circuit 15 through and beyond its peak resonance point by a predetermined amount and of thereafter removing the independent control voltage and substituting therefor the balanced output from the differential D. C. amplifier 34. The starting circuit 42 also performs the function of internally unbalancing the differential relay 35 at the start of the alignment cycle. To perform these functions the starting circuit 42 is connected to the reversing relay circuit 43 over the conductors 52 and 52a and to the differential D. C. amplifier 34 by means of the conductors 50 and 50a.

The square wave produced by the chopping circuit 31

is also supplied to the A. C. amplifier 32 over the conductor 29 which latter unit performs the function of amplifying the square wave to a suitable value. The output of the A. C. amplifier is supplied to the balanced keyed rectifier circuit 33 over the conductor 48 which latter unit performs the function of reconverting the amplified square wave into a pair of balanced unidirectional control voltages. To perform this function the balanced keyed rectifier 33 is supplied with both positive and negative square waves from the square wave generator 41 over the conductors 40 and 47.

The differential D. C. amplifier 34 is connected to the balanced keyed rectifier circuit 33 over the conductors 49 and 49a and performs the function of amplifying the output thereof and supplying amplified balanced control voltages to the differential relay 35 over the conductors 50 and 50a. The differential D. C. amplifier also performs the additional function of supplying balanced control voltages to the starting circuit 42 over the conductors 50 and 50a to control the motor 25 after the circuit 15 is tuned beyond its maximum response point by a predetermined amount.

The differential relay 35 is controlled by the differential D. C. amplifier 34 and the starting circuit 42 and performs the function of controlling the starting circuit 42 to remove the independent control voltage from the motor 25 when the circuit 15 is tuned beyond its peak resonance point by a predetermined amount. The differential relay also performs the function of supplying a control pulse over the conductor 51 to the reversing counter circuit 45 each time the circuit 15 is tuned through the peak response point.

The reversing relay circuit 43 is controlled by the reversing counter circuit 45 and the starting circuit 42 and performs the function of reversing the polarity of the balanced control voltages supplied thereto from the differential D. C. amplifier 34 each time the tuned circuit 15 is tuned through its peak response point to effect reversal of the motor 25 and hence of the direction of tuning of the circuit 15. To perform this function the reversing relay circuit 43 is connected to the starting circuit 42 by means of the conductors 52 and 52a; to the reversing counter circuit 45 by means of the conductor 55 and to the motor driving circuit 44 by means of the conductors 53 and 53a. The motor driving circuit supplies current to the split field windings of the motor 25 over the conductors 54 and 54a to control the speed and direction of rotation thereof and thereby control the tuning of the circuit 15.

OPERATION OF THE SYSTEM OF FIG. 1 AS A WHOLE

Briefly to consider the general mode of operation of the automatic alignment system of Fig. 1 described above, the alignment cycle is started by depressing the starting switch 500 which energizes the starting relay of the starting circuit 42. When the starting relay of the circuit 42 is energized there is produced an internal unbalance in the differential relay 35 which causes this relay to close in a predetermined direction and thereby to close a holding circuit which holds the starting relay closed after the starting switch 500 is released. Energization of the starting relay also causes an initial driving voltage of predetermined magnitude and polarity to be supplied to the motor driving circuit 44, whereupon the motor 25 drives the tuning slug 24 in the correct direction to tune the circuit 15 toward its peak response point. In this connection it will be understood that the tuning slug 24 may be positioned at one extremity of the coil 16 before the start of the alignment cycle and the polarity of the voltage supplied to the motor 25 so chosen that the tuning slug moves into the coil 16 so as to tune the circuit 15 in the correct direction.

As the resonant frequency of the circuit 15 is varied in the manner described above, the voltage produced across the detector load circuit 19 and 21 becomes in-

creasingly negative with respect to ground potential as the resonant frequency of the circuit 15 approaches more closely the frequency of the alignment signal from the generator 11. If the tuning slug is moved completely through the coil 16 the gradually changing detector voltage takes the form of a conventional resonance curve having a maximum or peak which corresponds to the alignment signal frequency as will be readily apparent to those skilled in the art.

Assuming that the output from the comparison bridge 30, as initially adjusted, is equal to zero at the start of the alignment cycle, as the detector voltage increases negatively in the manner described above, the negative output from the comparison bridge causes the memory condenser to be charged until the voltage across the memory condenser is equal to the detector voltage at which time the output from the comparison bridge is equal to its initial or zero value and charging of the memory condenser is halted. As the detector voltage continues to increase negatively, the memory voltage increases in the manner described above and effectively follows the detector voltage up to the peak response point. However, after the peak response point is passed the detector voltage becomes increasingly less negative whereas the memory condenser remains charged to the maximum negative detector voltage so that the output from the comparison bridge becomes positive with respect to its initial value and continues to increase positively as the circuit 15 is tuned further and further beyond the desired peak response point.

The output from the comparison bridge is then used to rebalance the differential relay 35 and reverse the direction of rotation of the motor 25 after which the comparison bridge output is used as an error signal to control the speed of the motor 25 so as to tune the circuit 15 back to its peak response point. To accomplish these functions, the increasing positive voltage produced by the comparison bridge 30 as the circuit 15 is tuned further beyond the peak response point, is converted into a square wave of corresponding amplitude and sense in the chopping circuit 31, amplified in the A. C. amplifier 32, and reconvered in the balanced keyed rectifier 33 into a pair of balanced unidirectional control voltages which are further amplified in the differential D. C. amplifier 34 and supplied to the differential relay 35 in the proper polarity to overcome the internal unbalance of the differential relay produced at the start of the alignment cycle. Accordingly, when the circuit 15 has been tuned beyond its peak response point by an amount sufficient to overcome the internal unbalance initially given to the differential relay 35, this relay opens, the initial driving voltage is removed from the motor driving circuit 44 and the amplified error signal from the differential D. C. amplifier 34 is substituted therefor and is used to control the tuning of the circuit 15 back to its peak response point. Also, when the differential relay 35 opens, the internal unbalance initially made therein is removed and the differential relay closes in the opposite direction due to the continued application of the error signal applied thereto from the differential D. C. amplifier 34.

When the motor 25 has tuned the circuit 15 back to its peak response point the error signal from the comparison bridge 30, which now controls the motor 25, falls to zero and the motor stops with the tuning slug positioned at the desired peak response point. If the mechanical driving system possesses sufficiently low inertia, the driving motor stops precisely at the peak resonance point and the alignment cycle is completed. However, if the mechanical system possesses substantial inertia, as is the practical case, the driving motor will not stop when the error signal from the comparison bridge reaches zero but instead will coast beyond the peak response point and an error signal is again produced by the comparison bridge. The polarity of this error signal produced by overshoot of the motor 25 is still of positive polarity due to the fact that the de-

tector voltage becomes positive with respect to the memory voltage on both sides of the peak response point. Accordingly, it is necessary to reverse the polarity of the error signal each time the circuit 15 is tuned through the peak response point in order to effect reversal of the motor 25 and tune the circuit 15 back to its peak response point. This last mentioned function is performed by the differential relay 35, the reversing counter circuit 45 and the reversing relay circuit 43. Thus, the positive error signal from the comparison bridge, which is amplified in the units 31, 32, 33 and 34 in the manner described above, goes to zero each time the circuit 15 is tuned through the peak response point. Each time the error signal goes to zero the differential relay 35 opens and thereafter closes in the same direction as the error signal becomes increasingly positive after the peak response point is passed. Each time the differential relay 35 opens and closes it produces a control pulse which is used to control the reversing counter circuit and effect a reversal of the reversing relay 43 which in turn reverses the polarity of the amplified error signal which is supplied from the differential D. C. amplifier 34 to the motor driving circuit 44.

If the driving system again overshoots the peak response point the polarity of the voltage supplied to the motor driving circuit 44 is again reversed as the differential relay opens and closes when passing through the zero error signal or peak response point. Such operation continues until the output from the differential D. C. amplifier is insufficient to drive the motor 25 at which time the tuning slug is accurately positioned at the maximum response point of the circuit 15.

In order to render the mode of operation of the automatic alignment system of Fig. 1 more readily understandable, there is shown in Figs. 2(a) and 2(b) the detector voltage and memory voltage characteristics produced in the system of Fig. 1. Referring to Fig. 2(a), the voltage produced across the detector load circuit 19 and 21 of the receiver 10 is therein illustrated and is plotted as a function of time. The initial voltage across the resonant circuit 15 coincides substantially with zero or ground potential, as indicated by the line 60, thus indicating that the resonant frequency of the circuit 15 is so far removed from the frequency of the signal generator 11 that there is substantially no response by the resonant circuit at this frequency. As the tuning slug is moved in the direction of the peak response point in the manner described heretofore, the detector voltage increases in the negative direction as indicated by the curve 61. After the peak response point is reached, which point is illustrated in Fig. 2(a) as occurring at the time t_1 , the detector voltage again decreases as indicated by the curve 62. It will be seen from an examination of Fig. 2(a) that the portions 61 and 62 of the detector voltage curve constitute a segment of the conventional single peaked resonance curve of a resonant circuit as it is tuned through resonance.

As the detector voltage builds up in the negative direction as indicated by the curve 61 in Fig. 2(a), the voltage across the memory condenser follows the detector voltage as illustrated in Fig. 2(b). Referring to Fig. 2(b), the memory condenser is initially short-circuited as hereinafter explained so that there is zero voltage across it as indicated by the line 70. As the detector voltage increases in the negative direction, the voltage across the memory condenser also increases along the curve 71. However, after the peak response point is reached, which point is again illustrated in Fig. 2(b) as occurring at the time t_1 , the voltage across the memory condenser remains constant as indicated by the portion 72. Thus the memory condenser voltage may be utilized as a reference voltage indicative of the peak response of the tunable circuit 15.

Referring again to Fig. 2(a), when the tuning slug is moved beyond the peak response point by an amount sufficient to produce a positive error signal from the comparison bridge 30 of sufficient amplitude to overcome the original internal unbalance made in the differential relay

35, this relay opens. The first opening of the differential relay 35 is illustrated in Fig. 2(a) as occurring at the time t_2 at which time the detector voltage is positive with respect to the memory circuit voltage by an amount A which is sufficient exactly to balance the differential relay and cause it to open. When the differential relay opens at time t_2 the internal unbalance is removed and the relay closes in the opposite direction and effects reversal of the motor 25 so that the circuit 15 is tuned back toward the point of maximum response. Accordingly, the detector voltage increases negatively again along the line 63 until it is again equal to the memory circuit voltage at time t_3 . If the mechanical driving system possesses very little inertia the tuning slug will not be driven beyond the peak response point 64 and hence the circuit 15 is accurately aligned to the desired peak response point.

If the driving system possesses substantial inertia, the tuning slug will be driven beyond the maximum response point 64 and the detector voltage will again increase along the opposite slope of the response curve as indicated at 65. When the tuning slug is overdriven so as to produce a positive response as indicated at 65, the differential relay again closes, having previously opened as the maximum response point 64 is reached, and supplies a control pulse to the reversing counter circuit 45 to effect reversal of the reversing relay 43 and reverse the direction of movement of the tuning slug. If the direction of movement of the tuning slug were not reversed, the positive going voltage 65 would tend to drive the tuning slug further away from the maximum response point 64. However, when the differential relay is closed after passage through the maximum response point 64, the reversing counter circuit 45 is actuated in the manner described above so that the direction of movement of the tuning slug is again reversed at time t_4 . The tuning slug is thus successively reversed at times t_4 and t_5 as it passes back and forth through the peak response point and the tuning slug eventually comes to rest at a position such that the detector voltage is exactly equal to the memory voltage and the circuit 15 is tuned exactly to peak resonance.

DETAILED DESCRIPTION OF THE SYSTEM OF FIG. 1

In considering the detailed circuitry of the system components briefly described above, operation of these components will be analyzed in so far as possible in terms of the functions which they perform in tuning the resonant circuit 15 to the alignment signal of the generator 11. Before considering the details of the system components, however, it is pointed out generally that corresponding reference characters have been used throughout the drawings to identify corresponding circuit elements of the system. It is also pointed out that while single conductors have been illustrated as inter-connecting the units shown in block diagram form in Fig. 1, all of the units are connected to the common ground potential indicated in each of the detailed schematic diagrams. Furthermore, unless necessary to an understanding of the operation of a particular system component, those circuit elements which perform entirely conventional functions in the circuit, namely functions which will be readily understood by those skilled in the art, have not been identified in the drawing nor referred to in the following description of the system components.

Comparison bridge 30

As previously pointed out in the general description of the system of Fig. 1, the comparison bridge 30, which is shown in detail in Fig. 3 of the drawings, performs the function of comparing the detector voltage derived from the tunable circuit 15 and a voltage derived from the memory circuit 38 and provides an output voltage equal to the difference therebetween. The output from the detector load circuit 19 and 21 is connected over the conductor 12 to the comparison bridge circuit 30 and

through a filter circuit indicated generally at 77 to the control electrode of an electron discharge tube 78. The filter circuit 77 is provided to reduce the response of the system to noise disturbances and extraneous voltages which may be present in the detector circuit of the receiver. More specifically, the filter circuit 77 comprises a parallel T network and includes a first T section comprising the resistors 79 and 80 and a capacitor 81, and a second T section comprising the capacitors 82 and 83 and the resistor 84, the second T section being connected in parallel with the first T section to the control electrode of the tube 78. The filter circuit 77 suppresses noise disturbances which may appear on the conductor 12 and the circuit constants thereof may be so proportioned as to provide substantially zero transmission at a particular frequency, as will be readily apparent to those skilled in the art. The zero transmission, or null point of the filter network 77 is so chosen that the filter circuit substantially suppresses voltages of line frequency which tend to interfere with the chopping circuit 31. In this connection, it will be understood that the voltage derived from the detector load circuit of the receiver comprises a gradually varying unidirectional voltage of very low frequency and this gradually varying voltage is transmitted through the filter circuit 77 substantially without change.

The cathode of the tube 78 is connected through a resistor 83 to a source of potential $-V$ which is negative with respect to ground potential. The anode of the tube 78 is connected to the B+ supply. The memory voltage produced in the memory circuit 38 is supplied over the conductor 14 to the control electrode of an electron discharge tube 91. The anode of the tube 91 is connected to the B+ supply and the cathode of the tube 91 is connected through a resistor 92 to ground potential. The cathode of the tube 78 is directly connected to the control electrode of an electron discharge tube 93, and the cathode of the tube 91 is directly connected to the control electrode of an electron discharge tube 94. The anodes of the tubes 93 and 94 are connected to the B+ supply. The cathodes of the tubes 93 and 94 are directly connected together and are connected through a common cathode resistor 95 to the negative potential $-V$. An output voltage from the comparison bridge circuit is derived from the commonly connected cathodes of the tubes 93 and 94 and is supplied over the output conductor 13 to the chopping circuit 31.

Considering now the operation of the above-described comparison bridge circuit, the output voltage from the detector circuit of the receiver, which is proportional to the instantaneous response of the tunable circuit 15, is transmitted through the filter circuit 77 to the tube 78 which acts as a cathode follower and produces across its cathode resistor 85 a voltage of the same phase as the detector voltage. Likewise, the memory voltage produced in the memory circuit 38 is supplied to the tube 91, which tube acts as a cathode follower and produces across its cathode resistor 92 a voltage of the same phase as the memory voltage. The control electrodes of the tubes 93 and 94 are respectively supplied with the output voltages from the cathode followers 78 and 91 and the two voltages are combined in the common cathode resistor 95. Inasmuch as the detector circuit of the receiver is so connected as to produce a negative output with respect to ground, the potential supplied to the cathode follower 78 and hence to the control electrode of the tube 93 comprises a unidirectional voltage which increases in the negative direction as the tuning slug is moved in the direction of the maximum response point of the circuit 15. While the memory condenser voltage is illustrated in Fig. 2(b) as comprising a negative going voltage with respect to ground, the actual memory circuit voltage supplied over the conductor 14 from the memory circuit 38 to the comparison bridge 30 is reversed in polarity and increases in the positive direction as the detector voltage increases in the negative direction, as

will be described in more detail in connection with the memory circuit 38. Accordingly, as the circuit 15 is tuned to its peak response point the negative going detector voltage is balanced by the positive going memory circuit voltage so that the voltage on the output conductor 13 of the comparison bridge 30 tends to remain constant during periods when the instantaneous response of the circuit 15 is increasing in the negative direction. However, when the peak response point is passed, the memory circuit voltage remains at its peak positive value and the detector voltage becomes less negative so that the voltage on the conductor 13 becomes increasingly positive as the circuit 15 is tuned further and further away from the peak response point. The comparison bridge circuit 30 thus provides a differential control voltage which is equal to the difference between the detector voltage, i. e., the instantaneous response of the tunable circuit 15, and the memory voltage produced by the memory circuit 38.

Chopping circuit 31

This circuit is shown in detail in Fig. 4 of the drawings and, as discussed briefly in the general description of the system of Fig. 1, is provided for the purpose of converting the gradually varying output voltage from the comparison bridge 30 into a square wave of corresponding amplitude and sense.

The gradually varying voltage which is derived from the tunable circuit 15 is of relatively low amplitude and of practically zero frequency. While such a low frequency voltage may be amplified by suitable direct coupled amplifiers, such an arrangement would be a source of instability and would not lend itself to the derivation of a reference voltage in the memory circuit 38 by charging a storage capacitor at periodic intervals so as to follow the instantaneous response of the circuit 15. Accordingly, the chopping circuit 31 is provided to convert the error voltage from the comparison bridge 30 into a square wave of corresponding amplitude and sense which may be amplified in A. C. coupled amplifiers and may be used to control the memory condenser charging circuit.

The chopping circuit 31 comprises a vibratory element, or armature 98, which is polarized so as to be moved back and forth between the fixed contacts 99 and 100 due to the attraction and repulsion of the magnetic field set up by the adjacent armature coil 101. The coil 101 is excited with a sinusoidal voltage from the standard frequency oscillator 39 so that the armature 98 is moved back and forth at the frequency of the oscillator 39. The fixed contact 99 is connected to the input terminal 97 to which is supplied voltage from the comparison bridge circuit 30 over the conductor 13. The fixed contact 100 is connected to the arm 105 of a potentiometer 106, one end of which is connected in series with the resistor 108 to the negative supply potential $-V$ and the other end of which is connected through the resistor 107 to the positive B+ supply. The vibratory element 98 is electrically connected over the conductor 109 and through a filter network indicated generally at 121 to the control electrode of a cathode follower output tube 122. The filter circuit 121 comprises a series of high-pass filter sections which operate to select the high frequency components of the square wave derived from the vibratory element 98. The tube 122 is provided with a cathode output resistor 123 across which the square wave from the vibratory element 98 is repeated in similar phase. The square wave produced across the resistor 123 is supplied directly to the A. C. coupled amplifier 32 over the conductor 20. Also, the square wave produced across the resistor 123 is connected through a plural section low-pass filter indicated generally at 124 and over the conductor 20a to the gating amplifier 36.

Considering now the operation of the chopping circuit 31, as the vibratory element 98 is moved back and forth between the contacts 99 and 100 under the influence of the sinusoidal voltage from the oscillator 39 it is suc-

sively connected to the potentials at which these contacts are operated. Therefore, during periods when the contacts 99 and 100 are not at the same potential, a square wave of voltage is produced on the output conductors 20 and 20a of the chopping circuit having a frequency corresponding to the frequency of the oscillator 39. The square wave thus produced is filtered in the input and output circuits of the cathode follower output tube 122 to remove contact noise voltages which arise when the contacts 98, 99 and 100 open and close.

The potential of the fixed contact 100 is initially adjusted by movement of the arm 105 of the potentiometer 106 to coincide exactly with the output voltage from the comparison bridge circuit at the start of the alignment cycle. Thus, when the output voltage from the detector circuit 19 and 21 is at substantially ground potential, i. e., when there is practically no voltage produced across the resonant circuit 15, and the storage capacitor of the memory circuit 38 is shorted out as hereinafter explained so that no voltage exists thereacross, the potential of the contact 100 is made equal to the potential of the contact 99 so that no variation in potential exists on the conductor 109 of the chopping circuit as the vibratory element 98 moves back and forth between the contacts 99 and 100.

When the output voltage from the comparison bridge circuit increases in the negative direction, i. e., when the resonant circuit 15 is tuned toward the peak response point, the potential of the contact 99 becomes less than the potential of the contact 100 and hence there is produced on the conductor 109 a square wave having an amplitude equal to the difference in potential between the contacts 99 and 100 and having a frequency equal to the frequency of the oscillator voltage supplied to the armature coil 101. The square wave thus produced on the conductor 109 is of the so-called symmetrical type, i. e., having equal on and off intervals due to the fact that the armature 98 is connected to the contacts 99 and 100 for equal intervals of time. Once the chopping circuit is initially adjusted, the square wave produced when the contact 99 is negative with respect to the contact 100 may be called a negative going square wave. When the potential of the contact 99 rises above the potential of the contact 100, a condition which occurs after the peak response point has been reached and the peak memory voltage has been established, the square wave output from the chopping circuit 31 changes in polarity and becomes a positive going square wave having an amplitude equal to the potential difference between the contacts 99 and 100 and having the same frequency as before. The chopping circuit thus operates to convert the unidirectional voltage produced by the comparison bridge circuit 30 into a square wave having an amplitude and sense which is representative of the departure of the comparison bridge output voltage from its initial value.

Gating amplifier 36

As discussed briefly in the general description of the system of Fig. 1, the gating amplifier 36, which is shown in detail in Fig. 5 of the drawings, is provided for the purpose of selecting from the output of the chopping circuit 31 only those square waves which occur when the contact 99 is negative with respect to the contact 100, i. e., when the output from the chopping circuit comprises a negative going square wave. The gating amplifier 36 also amplifies and shapes the selected signal so that it will properly initiate charging of the storage condenser of the memory circuit 38.

As shown in Fig. 5, the output signal from the chopping circuit 31 is supplied over the conductor 20a and through the coupling condenser 110 to the control electrode of an amplifier tube 125 and is repeated across the anode load resistor 126 of the amplifier tube 125 in amplified form. The amplified signal thus produced at the anode of the tube 125 is coupled through a condenser

127 to a squaring circuit including the tubes 128 and 129. The cathodes of the tubes 128 and 129 are connected together and are connected through the series resistors 131 and 132 to the negative potential -V. The control grid of the tube 129 is connected to the junction point of the resistors 131 and 132 so that the voltage across the common cathode resistor 131 acts as a bias voltage for the tube 129. The amplified signal supplied to the control grid of the tube 128 which, it will be recalled, is substantially a sine wave due to the filtering action of the networks 121 and 124 of the chopping circuit 31, is squared up in the circuit including the tubes 128 and 129 and there is produced across the anode load resistor 133 of the tube 129 a squared signal of similar phase to that impressed upon the control grid of the tube 128.

The squared output signal derived from the anode of the tube 129 is impressed upon the control grid 136 of a gating tube 137 through the coupling condenser 135. In order to bias the control grid 136 negatively, this grid is connected through the resistors 138 and 139 to the negative source of potential -V and the resistor 140 is connected from the junction point of the resistors 138 and 139 to ground potential. In order to bias the suppressor grid 141 of the gating tube 137 negatively, this grid is connected through the resistors 142 and 143 to the negative source of potential and a resistor 144 is connected from the junction point of the resistors 142 and 143 to ground potential.

A positive-going square wave is supplied from the square wave generator 41 over the conductor 40 to the suppressor grid 141 of the gating tube 137 to render this tube conductive only during a predetermined portion of each cycle of the chopping circuit signal. In this connection it will be understood that the square wave generator 41 is synchronized by suitable pulse generator means or the like with the sine wave oscillator 39 which controls the chopping circuit 31, so as to provide positive and negative-going square waves of the same frequency and phase as the sine wave supplied from the oscillator 39 to the armature coil 101 of the chopping circuit 31. The signals which are passed by the gating tube 137 and which are developed across the anode load resistor 147 thereof, are coupled through the condenser 151 to a second squaring circuit including the tubes 152 and 153. The squaring circuit including the tubes 152 and 153 is substantially identical to the first squaring circuit discussed above and performs the function of sharpening the sides of the signal passed by the gating tube 137. The gated and squared output signal is derived at the anode of the tube 153 and is supplied through the coupling condenser 154 and over the conductor 27 to the switching circuit 37.

Considering now the manner in which the gating tube 137 operates to select only those signals from the chopping circuit which are produced during periods when the contact 99 is negative with respect to the contact 100, it will be recalled that the output signal from the chopping circuit 31 is essentially a sine wave having a negative portion corresponding to the period when the movable contact 98 is connected to the contact 99 and having a positive portion when the movable contact 98 is connected to the fixed contact 100. The output signal from the chopping circuit is amplified and inverted in the tube 125 and the squaring circuit including the tubes 128 and 129 provides a steep-sided wave having a positive-going portion during the desired interval. The control grid 136 and the suppressor grid 141 of the gating tube 137 are operated at bias potentials which are sufficiently negative to cause the tube 137 to be continuously cut off. However, when a positive signal from the squaring circuit 128 and 129 coincides with the positive portion of the square wave supplied from the square wave generator 41 to the suppressor grid 141, the gating tube 137 conducts and produces a negative-going signal across the anode resistor 147 thereof. The selected signal is

further squared in the second squaring circuit including the tubes 152 and 153 so that a sufficiently steep-sided negative-going signal is supplied to the switching circuit 37 to turn on this circuit.

Switching circuit 37

As discussed briefly in connection with the general description of the system of Fig. 1, the switching circuit 37, which is shown in detail in Fig. 6 of the drawings, is provided for the purpose of controlling the charging of the memory storage condenser.

While the electronic switching circuit of Fig. 6 may comprise any suitable circuit arrangement for controlling the charging of the memory condenser, it is preferred to employ a flip-flop circuit, commonly known as an Eccles-Jordan trigger circuit, which circuit is modified in a manner to be described hereinafter to provide proper operation with the gating amplifier 36 and the square wave generator 41. Generally speaking, the switching circuit 37 comprises a pair of electron discharge tubes 157 and 158 which are interconnected so as to be switched abruptly from a conductive to a non-conductive state in response to negative control pulses supplied to the suppressor electrodes thereof. More specifically, the anode of the tube 157 is connected through a resistor 160 to the B+ supply and is connected through a resistor 161 to the control electrode of the opposing tube 158. The control electrode of the tube 158 is further connected through a resistor 162 to ground potential and through a resistor 163 to the negative source of potential -V. In a similar manner, the anode of the tube 158 is interconnected with the control electrode of the tube 157 by the voltage divider network including the resistors 164, 165, 166 and 167. The values of the circuit constants in the voltage divider network including the resistors 160, 161, 162 and 163 are so chosen that conduction of one tube produces a potential at the control electrode of the other tube which is sufficient to bias the other tube beyond anode current cutoff. However, if a negative pulse is supplied to the suppressor electrode of the conducting tube, the anode current in that tube is reduced so that the circuit abruptly switches to the opposite condition and the conducting tube becomes non-conductive and the non-conductive tube becomes conductive. Accordingly, if negative pulses are supplied to the suppressor grids of the tubes 157 and 158, these tubes are successively switched from a conductive to a non-conductive state.

The switching circuit 37 is turned on by means of the negative signal passed by the gating amplifier 36. Thus, the negative going output signal from the gating amplifier 36 is supplied over the conductor 27 to the suppressor grid of the tube 158 of the switching circuit 37. The switching circuit 37 is turned off by means of a positive square wave which is supplied from the square wave generator 41, over the conductor 40 and through the differentiating network including the condenser 168 and the resistor 169 to the suppressor grid of the tube 157. In this connection it will be understood that the switching circuit 37 is only responsive to negative pulses which are supplied to the suppressor grid of the conducting tube. Thus, if a negative pulse is supplied to the tube 157 when that tube is already non-conductive, the pulse will have no effect and will not key the switching circuit 37 to the opposite position.

When the tube 158 is in a conductive state, the control grid thereof is at substantially ground potential due to the current limiting action of the control grid of this tube. However, when the tube 158 is in a non-conductive state, the potential at the control grid of this tube is highly negative with respect to ground, as discussed above. Accordingly, as the switching circuit 37 is keyed from one position to the other, the potential at the control grid of the tube 157 is abruptly changed from substantially ground potential to a relatively large negative potential

and the control grid potential may be utilized as a control wave to control the charging of the memory circuit storage condenser. Accordingly, the control grid potential of the tube 158 is supplied directly over the conductor 28 to the memory circuit 38.

Memory circuit 38

As discussed generally in connection with the general description of the system of Fig. 1, the memory circuit 38, which is shown in detail in Fig. 7 of the drawings, is provided for the purpose of establishing a memory or reference voltage which is representative of the maximum or peak response of the tunable circuit 15.

Thus, referring to Fig. 7, there is provided a memory storage condenser 175 which is charged to provide a memory or reference voltage. The memory condenser 175 may be shorted out at the start of the alignment cycle by any suitable means, such as by the switch 179 which is connected across the condenser 175 so as to remove any charge from the condenser 175 at the start of the alignment cycle. One terminal of the memory condenser 175 is connected to the anode of a diode tube 176, the cathode of the tube 176 being connected through the resistors 177 and 178 to the negative source of potential -V. The potential of the cathode of the diode 176 is controlled by means of a charging tube 181, the cathode of which is connected to the junction of the resistors 177 and 178 and the anode of which is connected directly to the B+ supply. The charging tube 181 is in turn controlled by the control wave from the switching circuit 37, which is connected directly over the conductor 28 to the control grid of the charging tube 181.

The other side of the condenser 175 is connected through the resistors 182 and 183 to ground potential. The diode side of the condenser 175 is also connected to a control grid 184 of a reading tube 185. Preferably the reading tube 185 is of the pentagrid type, the cathode thereof being connected to the junction point of the resistors 182 and 183, the first control grid 187 and the fifth grid 186 being connected to the cathode and the second and fourth grids 188 and 189 being connected through the resistor 190 to ground potential and to the positive terminal 192 of an independent source of operating potential for the memory circuit 38. The anode of the reading tube 185 is connected through the resistor 191 to the positive supply terminal 192, the negative terminal 193 of the supply potential being connected through the filaments of the tubes of the memory circuit to the resistor 182. A memory circuit voltage is derived at the anode of the reading tube 185 and is supplied over the conductor 14 to the comparison bridge 30 in the manner described generally heretofore.

Considering first the operation of the above-described memory circuit per se, the charging tube 181 operates as a cathode follower and repeats across the cathode resistor 178 the charging control wave produced by the switching circuit 37. Inasmuch as the memory charging condenser 175 is directly connected through the filament circuits to the negative terminal 193, the anode of the diode 176 is also at this relatively large negative potential immediately after the shorting switch 179 is opened. Accordingly, when the cathode of the charging tube 181 is at a relatively high positive potential, that is during the positive portions of the charging control wave which is repeated across the resistor 178, the cathode of the diode 176 is positive with respect to the anode thereof, the diode 176 remains non-conductive and the memory condenser 175 is not charged.

However, during the negative portions of the charging control wave, the cathode potential of the diode 176 is reduced below the anode potential thereof so as to produce a charging path for the memory condenser 175. This charging path includes the diode 176, the resistors 177 and 178, the negative potential source -V, and the resistors 182 and 183. Inasmuch as the output im-

pedance of the cathode follower charging tube 181 is of relatively low value, the resistor 177 effectively controls the rate at which the memory condenser 175 is charged from the independent voltage source -V. As the memory condenser 175 is charged through the diode 176, the potential of the control grid 184 of the reading tube 185 becomes more negative thus reducing the flow of current through the anode load resistor 191 thereof and causing a corresponding positive increase in the potential at the anode of the reading tube 185. In order to prevent the memory condenser 175 from discharging once it is charged to a voltage representative of the peak response of the circuit 15, the reading tube 185 is preferably of the type having a relatively small control grid current and the reading tube is operated at low filament and anode supply voltages.

OPERATION OF THE SEQUENTIAL MEMORY SYSTEM OF FIG. 1

Considering now the manner in which the comparison bridge 30, the chopping circuit 31, the gating amplifier 36, the switching circuit 37 and the memory circuit 38 cooperate to provide a memory voltage which is representative of the maximum response of the tunable circuit 15, it will be understood that the memory condenser 175 is initially short-circuited by the means of the switch 179 so as to produce zero voltage thereacross and the potential of the fixed contact 100 of the chopping circuit 31 is adjusted so as to be equal to the output voltage from the comparison bridge 30 under these conditions. Also, the tuning slug 24 is initially positioned at one end of the coil 16 and remote from the peak response point of the circuit 15.

As the tuning slug is moved toward the peak response point of the circuit 15, the detector voltage supplied over the conductor 12 to the comparison bridge 30 becomes more negative while the potential supplied over the conductor 14 from the memory circuit 38 to the comparison bridge is as yet unchanged. As a result, the potential produced on the output conductor 13 of the comparison bridge 30 becomes negative with respect to its initial value and accordingly, the potential of the contact 99 of the chopping circuit 31 becomes negative with respect to the potential of the contact 100. With the contact 99 at a negative potential relative to the contact 100, the chopping circuit 31 provides a negative-going square wave having an amplitude equal to this potential difference. The negative-going square wave thus produced is filtered in the input and output circuits of the cathode follower tube 122 and the resulting sine wave is amplified and inverted in the tube 125 of the gating amplifier 36 and squared up in the squaring circuit including the tubes 128 and 129 and is supplied to the control grid 136 of the gating tube 137.

The gating tube 137 conducts only upon a coincidence of a positive wave supplied to the control grid 136 and a positive wave supplied to the suppressor grid 141. Accordingly, the gating tube 137 conducts only during the coincidence of the positive portions of the inverted squared sine wave supplied to the grid 136 and the positive-going portions of the square wave supplied to the suppressor grid 141 from the square wave generator 41. There is thus provided at the anode circuit of the gating tube 137 a negative-going signal which coincides in time with the negative-going square wave produced by the chopping circuit 31. The negative signal passed by the gating tube 137 is sharpened in the squaring circuit including the tubes 152 and 153 and is utilized to turn on the switching circuit 37 by rendering the tube 158 thereof non-conductive. When the tube 158 is rendered non-conductive in the manner described above, the potential on the conductor 28 becomes negative and the diode 176 conducts so that charging of the memory condenser 175 is initiated.

Once the tube 158 is rendered non-conductive by the

negative signal supplied thereto from the gating amplifier 36, the suppressor grid of the tube 158 loses control and hence is incapable of terminating the charging period. It is therefore necessary to terminate the charging period of the memory condenser 175 by applying a negative shut-off pulse to the suppressor grid of the opposite tube 157 of the switching circuit 37. This negative shut-off pulse may be obtained in either of two ways depending upon the particular memory system which is employed. In the sequential memory system illustrated in Fig. 1, the negative shut-off pulse is obtained by differentiating the positive-going square wave supplied from the square wave generator 41 over the conductor 40 to the gating tube 137 and applying the differentiated square wave to the suppressor grid of the switching tube 157. Differentiation of the positive-going square wave produces a negative shut-off pulse coincident with the trailing edge of the positive-going square wave which operates to turn off the switching circuit and terminate the charging period of the memory storage condenser. The memory condenser is thus sequentially charged during the "on" periods of the positive-going square wave. The application of the differentiated positive-going square wave to the suppressor grid of the tube 157 also insures that the tube 158 is normally maintained in a conductive stage in readiness for negative signals supplied from the gating amplifier 36.

As the memory condenser 175 is charged sequentially during the "on" periods of the positive-going square wave, the voltage thereacross becomes increasingly negative and, accordingly, the voltage at the anode of the reading tube 185 becomes increasingly positive. The positively increasing voltage thus produced at the anode of the reading tube 185 is supplied over the conductor 14 to the comparison bridge so as to off-set the negatively increasing detector voltage supplied to the comparison bridge over the conductor 12. When the positive memory circuit voltage exactly balances the negative detector voltage the output from the comparison bridge 30 is equal to its initial, or zero, value, the output from the chopping circuit 31 is zero, and the memory storage condenser holds the charge acquired during the preceding sequential charging periods. In this connection it will be understood that the entire chain of events by means of which the memory condenser 175 is charged takes place very rapidly so that the memory circuit voltage follows faithfully the gradually varying detector voltage as it increases negatively up to the peak response point.

Up to this point it has been assumed that the instantaneous response voltage always changes in the negative direction, as the tuning slug is moved toward the maximum response point, and hence the output voltage from the chopping circuit 31 is always a negative going square wave. However, when the tuning slug passes the maximum response point, the detector voltage becomes more positive, while the memory circuit voltage remains at its maximum positive value, so that the output voltage from the comparison bridge circuit becomes more positive than its initial value and hence the chopping circuit 31 produces a positive going square wave. The positive going signal thus produced is amplified in the initial stages of the gating amplifier 36; however, it is not of the correct polarity to coincide with the gating pulses supplied to the suppressor grid 141 of the gating tube 137 and hence this positive going signal is not repeated in the output circuit of the device 137 and is not supplied to the switching circuit 37. Accordingly, the memory condenser 175 is not further charged as the instantaneous response voltage becomes more positive, but instead remains charged to a value which corresponds to the peak response point of the resonant circuit 15.

In order to correlate the above-described sequence of

memory system operations reference is now had to Figs. 8(a) and 8(b) and Figs. 9(a)-9(d), inclusive, wherein there is illustrated various wave forms which occur in timed relationship in the above-described circuits. Thus, Fig. 8(a) shows the sinusoidal wave 200 which is produced by the standard frequency oscillator 39 and which is utilized to synchronize the operation of the chopping circuit 31, the gating amplifier 36 and the switching circuit 37. While the standard frequency oscillator 39, which generates the sine wave 200, may be of any suitable type I prefer to employ a Wien bridge oscillator in which inverse feedback is utilized to provide an output voltage which is substantially independent of circuit parameters, supply voltages and tube characteristics, and wherein a stabilized amplitude of oscillation is achieved. The frequency of the sine wave 200 may be of the order of 60 cycles per second.

During the positive half cycles of the sine wave 200 the armature coil 101 (Fig. 4) attracts the vibratory armature 98 and connects the armature to the fixed contact 99 and, accordingly, supplies a potential of this value to the conductor 109 of the chopping circuit 31. During negative half cycles of the sine wave 200 the vibratory armature is repelled and makes contact with the fixed contact 100 and accordingly supplies a potential equal to the potential of the arm 105 to the conductor 109.

If the contact 99 is negative with respect to the contact 100, that is, if the comparison bridge output voltage is negative with respect to its initial value, the output from the chopping circuit is as illustrated in the first portion of the timing diagram of Fig. 8(b). As shown, the potential of the contact 100 is illustrated as having the value 201 and the potential of the contact 99 is illustrated as having the value 202, which value is negative with respect to the value 201 by an amount 203. There is thus produced a negative going square wave 204, which has a frequency equal to that of the sine wave 200 and an amplitude equal to the potential difference 203.

If the potential values 201 and 202 coincide, which situation obtains when the memory circuit voltage is equal to the detector voltage, there is no output voltage produced from the chopping circuit and the voltage output from the chopping circuit remains at the value 201. If the voltage from the comparison bridge becomes positive with respect to its initial value, so that the potential level of the contact 99 has a value 205 which is positive with respect to the terminal 100 by an amount 206, there is produced the positive going square wave 207 which is also of the frequency of the sine wave 200 and has an amplitude equal to the positive displacement 206. In this connection it will be understood that the amplitudes 203 and 206 are merely representative of particular instants in the alignment cycle and these amplitudes vary as the output voltage from the comparison bridge circuit varies gradually in either the negative or positive direction from its initial value. The negative going square wave 204 is utilized to control the charging of the storage capacitor which in turn increases the output of the comparison bridge circuit so that the negative square wave 204 is continuously appearing and disappearing as the storage capacitor voltage follows the negatively increasing detector voltage.

The sinusoidal wave 200 of Fig. 8(a) is likewise utilized to synchronize the output of the square wave generator 41 so that the square wave generator provides positive and negative square waves having the time relationships shown in Figs. 9(a) and 9(b). Thus, referring to Fig. 9(a) the square wave generator provides at the output terminal 112 thereof (Fig. 4) the positive going square wave 210 which is of the same frequency as the sine wave 200. Likewise, the negative output from the output terminal 113 of the square wave generator 41 (Fig. 4) comprises a negative going square wave 211 which is

shown in Fig. 9(b). It is evident that the square waves 210 and 211 are equal in amplitude and of opposite phase.

It will be apparent from a comparison of Fig. 8(b) and 9(a) that the negative going square wave 204 of Fig. 8(b) and the positive going square wave 210 of Fig. 9(a) are of equal duration and are coincident in time. The negative going square wave 204 from the chopping circuit which occurs during periods when the output from the comparison bridge is negative, is integrated and inverted in the gating amplifier and supplied to the control grid 136 of the gating tube 137. Likewise, the positive going square wave 210 (Fig. 9(d)) is applied to the suppressor grid 141 of the gating tube. The wave form thus produced in the anode circuit of the device 137 is illustrated in Fig. 9(d) and comprises a negative going clipped sine wave 212 which is repeated through the wave shaping circuit including the tubes 152 and 153 and is supplied to the switching circuit 37. The leading edge 213 of the clipped sine wave 212 operates to render the switching tube 158 non-conductive and hence to initiate charging of the storage capacitor of the memory circuit 38.

As discussed above, the clipped sine wave 212 is incapable of returning the switching circuit to its original condition inasmuch as the suppressor electrode to which

it is connected loses control after the switching operation. Accordingly, to turn off the switching circuit, the positive going square wave 216 from the square wave generator 41

is differentiated so as to provide the wave form shown in Fig. 9(c). Thus, referring to Fig. 9(c), the differentiated wave form comprises positive pulses 214 which correspond to the leading edges of the positive going square wave 210 of Fig. 9(a) and negative going pulses 215 which correspond to the trailing edges of the square wave 210. The differentiated square wave of Fig. 9(c)

is supplied to the suppressor grid of the tube 157 and the negative pulses 215 thereof operate to turn off the switching circuit and discontinue charging of the memory circuit condenser 175. It will be noted that the turn off pulses 215 occur continuously, regardless of the output

from the gating amplifier, and thus insure that the switching circuit is in condition for actuation by a subsequent negative going clipped sine wave 212 supplied by the gating amplifier 36.

Considering now the operation of the gating amplifier 36 when the chopping circuit supplies the positive going square wave 207 (Fig. 8(b)) it will be recalled that the square wave 207 is filtered and inverted in the gating

amplifier 36 and is applied to the grid 136 of the gating tube 137. However, when the sine wave corresponding to the square wave 207 is inverted the positive portions thereof do not coincide with the positive portions of the square wave 210 (Fig. 9(a)) and hence no output appears in the anode circuit of the gating device 137. Accordingly, the output from the gating amplifier remains at the initial value 216 thereof (Fig. 9(d)) during periods

when the comparison bridge output voltage is positive.

From the foregoing discussion, it is evident that the sequential memory system of Fig. 1 provides a reference voltage which is equal to the maximum or peak response of the tuned circuit 15 and may be used to control subsequent reversals in the direction of movement of the tuning slug to effect a final alignment of the tuning slug to the maximum response position. Up until the time that the tuning slug reaches the maximum response point the

output from the comparison bridge circuit is either negative with respect to or equal to its initial value, depending upon whether or not the memory condenser lags behind the detector voltage as it increases in the negative direction.

However, after the maximum response point is passed the memory condenser holds its charge and is used as a reference voltage to control subsequent movement of the motor 25.

A.C. amplifier 32

This circuit, which is shown in detail in Fig. 10 of the drawings and forms a part of the motor control system,

is substantially conventional and is designed to amplify the square wave produced by the chopping circuit 31. In this connection it will be recalled that in order to control the differential relay circuit 35 and the motor driving circuit 44 in accordance with the output from the comparison bridge circuit 30 it is necessary to amplify the square wave produced by the chopping circuit 31 and to reconvert the amplified square wave to a pair of balanced unidirectional control voltages which are of sufficient amplitude to control the differential relay circuit 35 and the motor 25.

Referring to Fig. 10, the filtered square wave, which is produced across the cathode resistor 123 of the chopping circuit 31, is supplied over the conductor 20 and through the coupling condenser 221 to the control electrode of a first amplifier tube 222. The tube 222 is biased for A. C. operation and there is derived at the anode of the tube 222 the signal from the chopping circuit in amplified form. The signal from the tube 222 is coupled through the condenser 223 to a second amplifier tube 224 and is repeated at the anode of the tube 224 in amplified form and is supplied over the conductor 48 to the balanced keyed rectifier circuit 33.

Balanced keyed rectifier circuit 33

As discussed generally in connection with the general description of the system of Fig. 1, the balanced keyed rectifier circuit 33, which is shown in detail in Fig. 11 of the drawings, is provided for the purpose of converting the amplified square wave from the chopping circuit into a pair of balanced unidirectional control voltages which may be utilized, after further amplification in the differential D. C. amplifier 34, to control the differential relay 35 and the motor driving circuit 44.

Referring to Fig. 11 of the drawings, the balanced rectifier 33 comprises a pair of electron discharge tubes 230 and 231, the control grids of which are connected together and are connected to ground through a common resistor 232. The amplified signal from the A. C. amplifier 32 is supplied over the conductor 48 and through the condenser 233 to the control grids of both of the tubes 230 and 231.

In order to control the balanced keyed rectifier output voltages in accordance with reversals in the polarity of the original square wave produced by the chopping circuit 31, the tubes 230 and 231 are supplied with square waves of opposite polarity from the square wave generator 41. Thus, the suppressor electrode of the tube 231 is supplied with a positive going square wave from the square wave generator 41 over the conductor 40 and through the coupling condenser 236. Likewise, the suppressor electrode of the tube 230 is supplied with a negative going square wave from the square wave generator 41 over the conductor 47 and through the coupling condenser 238. The cathode of the tube 230 is connected through a resistor 239 to the negative source of potential $-V$ and the cathode of the tube 231 is also connected through a resistor 240 to this negative potential. The anode of the tube 230 is connected through a resistor 241 to the B+ supply and the anode of the tube 231 is connected through a load resistor 242 to the B+ supply. In order to derive from the composite square waves produced in the anode circuits of the devices 230 and 231 a pair of unidirectional control voltages which are balanced with respect to a fixed reference level, there is associated with each anode circuit an integration network which filters the square waves so that a potential equal to the average value of the composite square waves is supplied to the output terminals of the rectifier circuit. Thus, the anode of the tube 230 is connected through a resistor 243 and a condenser 244 to the B+ supply and the junction point of the resistor 243 and the condenser 244 is further connected through a resistor 245 and a condenser 246 to the B+ supply. The junction point of the resistor 245 and the condenser 246 is connected to the output conductor

49 of the balanced rectifier circuit. Likewise, the anode of the tube 231 is connected through a resistor 248 and a condenser 249 to the B+ supply and the junction of these elements is further connected through a resistor 250 and a condenser 251 to the B+ supply. The junction of the elements 250 and 251 is connected to the other output conductor 49a of the balanced rectifier circuit.

Considering now the operation of the above described balanced keyed rectifier circuit, it will be understood that the amplified signal produced at the output of the A. C. amplifier 32 is supplied to the control grids of both of the tubes 230 and 231. However, these tubes are rendered conductive only during periods corresponding to the positive portions of the particular square wave supplied to the suppressor grid thereof and hence the tubes are alternately switched from a conductive to a non-conductive state, the tube 230 conducting when the tube 231 is non-conducting and vice versa. Inasmuch as the positive and negative square waves which are supplied to the suppressor grids of the tubes 230 and 231 from the square wave generator 41 are synchronized with the square wave amplified by the A. C. amplifier 32 and supplied to the control grids of these tubes, it is evident that the tubes conduct during different portions of the square wave cycle and hence there is produced in the anode circuits thereof square waves which are of substantially different amplitude. The average or unidirectional component of these square waves is derived in the integration circuits described above to provide a pair of unidirectional control voltages which vary in opposite directions from a fixed D. C. reference level in accordance with the amplitude and polarity of the incoming signal.

The above described derivation of balanced unidirectional control voltages may readily be understood by reference to Figs. 8(b), 9(a) and 9(b) wherein the time relationships of the square waves utilized in the rectifying circuit are shown. Thus, referring to Fig. 8(b), we may consider the positive going square wave 207 as representative of the square wave which is supplied to the control grids of the tubes 230 and 231 after the maximum response point has been passed and the memory circuit voltage is established. With the positive going square wave 210 (Fig. 9(a)) applied to the suppressor grid of the tube 231, it is evident that this tube will conduct during the positive portions of the square wave 210 during which interval of time the square wave 207 is also at a positive potential. Accordingly, the device 231 will draw a relatively large anode current and cause a corresponding relatively large anode drop in voltage across the anode load resistor 242 thereof. On the other hand, with the negative going square wave 211 (Fig. 9(b)) applied to the suppressor electrode of the tube 230, this tube will conduct only during the positive portions of the square wave 211 which portions correspond to the periods when the square wave 207 is at a negative potential. Accordingly the device 230 will draw a relatively small amount of anode current and the anode potential thereof will remain at a relatively high value. As the amplitude 206 of the square wave 207 varies it is evident from the foregoing discussion that the potentials derived from the anode circuits of the devices 230 and 231 will vary in opposite directions so as to provide balanced unidirectional voltages by a combination of the above-described square wave voltages. Thus, as the amplitude 206 of the square wave 207 increases, the output voltage applied to conductor 49a becomes more negative and the output voltage applied to the conductor 49 becomes more positive. When no square wave 207 is supplied to the tubes 230 and 231, i. e., when the tuning slug is exactly positioned at the peak response point and the detector voltage is exactly equal to the memory circuit voltage, the output voltages on the conductors 49 and 49a are equal due to the fact that the average values of the square waves 210 and 211 are equal. In this connection it will be understood that during the initial part of the alignment cycle the negative going square

wave 204 (Fig. 8(b)) is present and is rectified by the balanced rectifier circuit 33. However, the polarities of the output voltages are then reversed so that as the amplitude 203 of the square wave 204 increases, the output voltage on the conductor 49a becomes more positive and the output voltage on the conductor 49 becomes more negative.

Differential D. C. amplifier 34

As discussed generally in connection with the general description of the system of Fig. 1, the differential D. C. amplifier 34, which is shown in detail in Fig. 12 of the drawings, is provided for the purpose of amplifying the balanced control voltages produced by the balanced keyed rectifier circuit 33 to such a level that they may be used to control the differential relay circuit 35 and the motor driving circuit 44.

Referring to Fig. 12, one control voltage from the balanced rectifier circuit 33 is supplied over the conductor 49 to the control grid of an electron discharge tube 261. The other control voltage is supplied over the conductor 49a to the control grid of an electron discharge tube 263. The anodes of the tubes 261 and 263 are connected to the B+ supply and the screen grids thereof are connected together and are connected to the B+ supply through a resistor 264. The cathode of the tube 263 is connected through a potentiometer 265 and a resistor 266 to one contact 267 of a double-pole double-throw switch 268. Also, the cathode of the tube 261 is connected through a potentiometer 269 and a resistor 270 to another contact 271 of the switch 268. The contact 272 of the switch 268 is connected to the contact 271 and the contact 273 is connected to the contact 267. One center contact 274 of the switch 268 is connected to the source of negative potential -V and is further connected through a potentiometer 275 to the other center contact 276. By connecting the center terminals either to the terminals 271 and 273 or the terminals 267 and 272, the potentiometer 275 is connected in series with either the cathode circuit of tube 261 or the cathode circuit of the tube 263. By such an arrangement the cathode resistance of either tube may be varied for calibration purposes.

The tubes 261 and 263 operate as cathode followers and repeat across their respective potentiometers 265 and 269 the voltages supplied from the input conductors 49 and 49a. The arm 280 of the potentiometer 265 is directly connected to the control grid of an amplifier tube 281 and the arm 282 of the potentiometer 269 is directly connected to the control grid of an amplifier tube 283. The anode of the tube 281 is connected through a load resistor 284 to the B+ supply and the anode of the tube 283 is likewise connected through its load resistor 285 to the B+ supply. The cathode of the tube 281 is connected through a resistor 286 to the junction point of the potentiometer 269 and the resistor 270. Likewise, the cathode of the tube 283 is connected through a resistor 287 to the junction point of potentiometer 265 and resistor 266. The output voltage derived at the anode of the tube 281 is supplied to the output conductor 50 and the voltage derived at the anode of the tube 283 is supplied to the output conductor 50a.

In considering the operation of the above described differential D. C. amplifier, it will be understood that the tubes 261 and 263 operate as cathode followers and repeat across the cathode potentiometers thereof the unidirectional control voltages supplied to the control grids of these devices. The voltages produced at the control arms of the potentiometers 265 and 269 are directly coupled to the control grids of the tubes 281 and 283, and as the cathodes of these devices are also connected to the potentiometers, these unidirectional voltages are amplified in the tubes 281 and 283 and repeated across the anode resistors 284 and 285. The differential D. C. amplifier 34 amplifies the balanced or push-pull control voltages supplied from the balanced rectifier circuit 33; however, sig-

nals of the same sense, i. e. push-push signals are not amplified. Accordingly, noise voltages and line disturbances are not amplified in the amplifier 34 and relatively noise free push-pull control voltages are supplied to the differential relay circuit 35 and the motor driving circuit 44.

Differential relay circuit 35 and starting circuit 42

As discussed generally in connection with the general description of the system of Fig. 1, the differential relay circuit 35, which is shown in detail in Fig. 13 of the drawings, is provided for the purpose of de-energizing the starting relay of the starting circuit 42 when the circuit 15 has been tuned beyond the peak response point by a predetermined amount and also performs the function of supplying a control pulse to the reversing counter circuit 45 each time the circuit 15 is tuned through the peak response point. The starting circuit 42, which is also shown in detail in Fig. 13 of the drawings, is provided for the purpose of supplying an independent control voltage to the motor driving circuit 44 at the start of the alignment cycle. The starting circuit 42 also performs the function of unbalancing the differential relay at the start of the alignment cycle.

Referring to Fig. 13, one unidirectional control voltage from the differential D. C. amplifier 34 is supplied over the conductor 50 and through the parallel T filter network indicated generally at 296 to the control grid of an electron discharge tube 297. The other unidirectional control voltage from the differential D. C. amplifier 34 is supplied over the conductor 50a and through the parallel T filter network 299 to the control grid of an electron discharge tube 300. The tubes 297 and 300 operate to control the flow of current through a differential relay indicated generally at 301 which is interconnected with the starting circuit 42 and the reversing counter circuit 45. Thus, the anode of the tube 297 is connected through one winding 302 of the differential relay 301 to the B+ supply. Likewise, the anode of the tube 300 is connected through the other winding 303 of the differential relay 301 to the B+ supply. In order to permit initial balancing of the unidirectional currents of the tubes, the screen grids of the tubes 297 and 300 are connected to the ends of a potentiometer 304 and the arm of the potentiometer 304 is connected through a resistor 305 to the B+ supply. The cathode of the tube 297 is connected through an unbalancing resistor 306 to the cathode of the tube 300 and the cathode of the tube 300 is connected through a resistor 307 to ground potential.

The starting switch 500, of the starting circuit 42, is closed by the operator to initiate the alignment cycle. One side of the switch 500 is connected through the holding coil 315 of the starting relay 316 to ground potential. The other side of the switch 500 is connected through a resistor 317 to the B+ supply. The differential relay 301 is provided with a fixed contact 308 and a cooperating movable contact 309 which is connected to the holding coil 315.

The relay 316 is further provided with a movable contact 313 which is connected to the resistor 317 and a cooperating fixed contact 314 which is connected to the contact 308 of the relay 301. In addition, the differential relay is provided with a fixed contact 310 which is connected to the B+ supply, and with a cooperating movable contact 311 which is connected over the conductor 51 to the reversing counter circuit 45. The differential relay 301 is of the type in which the movable contacts 309 and 311 occupy a neutral position when the windings 302 and 303 are substantially equally energized, and is shown in Fig. 13 in the circuit closing position to which the contacts move when the energization of the winding 303 exceeds that of the winding 302.

The starting relay 316 is provided with a fixed contact 318 which is connected to the cathode of the tube 297

and a cooperating movable contact 319 which is connected to the cathode of the tube 300. The starting relay 316 is also provided with a fixed contact 320 which is connected to the conductor 50 and a fixed contact 321 which is connected to the conductor 50a. A voltage divider network including the resistors 322, 323, and 324 is connected from the B+ supply to ground potential so as to provide across the resistor 323 a unidirectional potential of the polarity indicated in Fig. 13. The starting relay 316 is further provided with a fixed contact 325 which is connected to the junction point of the resistors 323 and 324 and a fixed contact 326 which is connected to the junction point of resistors 322 and 323. The movable contact 327 of the relay 316, which cooperates with the fixed contacts 321 and 325, is connected to the output conductor 52a of the starting circuit 42 and the movable contact 329, which cooperates with the contacts 320 and 326, is connected to the output conductor 52 of the starting circuit 42.

Considering now the operation of the above-described differential relay circuit 35 and the starting circuit 42, upon closure of the starting switch 500, the starting circuit 42 performs two functions. The first of these functions is to unbalance the differential relay 301 in a given direction so as to hold in the starting relay 316. The second function is to apply an independent control voltage to the motor driving circuit 44 so as to cause the tuning slug to be driven in the direction of the maximum response point of the circuit 15. Inasmuch as this second function is more properly described in connection with the motor driving circuit 44 per se, a consideration of this second function will be made in connection therewith.

Considering the first function of the starting circuit 42, it will be recalled that at the start of the alignment cycle the comparison bridge 30 is balanced and the output voltage from the chopping circuit 31 is zero. Accordingly, the balanced control voltages supplied over the conductors 50 and 50a to the differential relay circuit 35 are equal and these voltages are at their initial, or reference level. The filter circuits 296 and 299, which are connected in series with the input circuits of the tubes 297 and 300 are of the parallel T type and are similar to the filter circuit 77 discussed in connection with the comparison bridge 30 (Fig. 3). The filter circuits 296 and 299 are provided for the purpose of eliminating interference from the power supply circuit. In order initially to balance the currents drawn by the tubes 297 and 300, with the additional resistor 306 short circuited by the normally closed contacts 318 and 319 of the starting relay 316, there is provided the potentiometer 304 which varies the screen potential supplied to the tubes 297 and 300 so as to equalize the currents drawn thereby so that the differential relay 301 will initially occupy its neutral position.

When the starting switch 500 is closed, the coil 315 is energized and the starting relay 316, which is shown in the open position in Fig. 13, closes, thereby opening the contacts 318 and 319 thereof, which normally short circuit the resistor 306, so that the resistor 306 is inserted in the cathode circuit of the tube 297. With the additional resistor 306 in the cathode circuit of the device 297, and with equal voltages applied to the input circuits of the tubes 297 and 300 as described above, the tube 300 draws more current than the tube 297 and the greater flow of current through the differential winding 303 of the relay 301 causes the contacts 308 and 309 to close. The contacts 308 and 309 are connected in shunt with the starting switch 500 through the contacts 313 and 314 so that the coil 315 remains energized even though the starting switch 500 is released by the operator. The contacts 308 and 309 of the relay 301 and the contacts 313 and 314 of the relay 316 thus operate as a holding circuit for the starting relay 316.

The relay 301 after closure in the direction shown

in Fig. 13 will remain in this position until the input voltages supplied to the tubes 297 and 300 become sufficiently unbalanced in the correct direction to equalize the currents drawn by these two tubes. Inasmuch as the current drawn by the tube 297 is smaller than that drawn by the tube 300, the control voltage supplied over the conductor 50 to the tube 297 must increase positively with respect to its initial or reference value in order to increase the current drawn by the tube 297 to a point where the current through the windings 302 and 303 are balanced before the relay 301 will open. In this connection it will be understood that the balanced control voltages on the conductors 50 and 50a are push-pull in character, and vary in opposite directions by equal amounts so that the voltage on the conductor 50a decreases at the same time as the voltage on the conductor 50 increases. However, the net effect of these balanced control voltages may be considered on a single ended basis as simply an increase in the voltage supplied over the conductor 50.

The potential on the conductor 50 is either equal to or more negative than its reference or initial value during the period when the tuning slug is moved from its initial position to the peak response point of the tunable circuit 15. This is readily apparent when it is realized that the output from the comparison bridge during this period is either equal to its initially adjusted value during periods when the memory condenser is exactly equal to the detector voltage or is negative with respect to its initial value during periods when the memory condenser voltage lags behind the detector voltage. Accordingly, it is not until the peak response point of the circuit 15 is passed that the control voltage supplied over the conductor 50 to the differential relay circuit 35 starts to increase and therefore the differential relay 301 remains closed in the position shown in Fig. 13 until after the peak response point is passed. However, when the circuit 15 has been tuned beyond the peak response point by an amount such that the control voltage on the conductor 50 is sufficiently positive to overcome the internal unbalance between the tubes 297 and 300, as determined by the cathode resistor 306, the currents drawn by these tubes are exactly equal and the differential relay 301 opens to its neutral position.

Opening of the contacts 308 and 309 of the relay 301 breaks the holding circuit for the relay winding 315 and causes a de-energization of the starting relay 316 whereupon the contacts 318 and 319 of the relay 316 close and the resistor 306 is short-circuited. When the resistor 306 is short-circuited, the tube 297 assumes control due to the fact that it is now drawing more current than the tube 300 and hence the differential relay 301 closes in the opposite direction so as to close the contacts 310 and 311 thereof. Upon closure of the contacts 310 and 311, B+ potential is supplied over the conductor 51 to the reversing counter circuit 45 to control the operation thereof as will be described in more detail in connection with Fig. 15. When the starting relay 316 is de-energized the contacts 313 and 314 thereof open so that subsequent closure of the contacts 308 and 309 of the differential relay 301 will not cause the relay 316 to be energized. Accordingly, once the circuit 15 has been tuned beyond its peak response point by a predetermined amount, the starting relay opens and remains in that position for the remainder of the alignment cycle.

Reversing relay circuit 43 and motor driving circuit 44

As discussed generally in connection with the general description of the system of Fig. 1, the reversing relay circuit 43, which is shown in Fig. 14 of the drawings, is provided for the purpose of reversing the control voltages which are supplied to the motor driving circuit 44 from the differential D. C. amplifier 34 each time the circuit 15 is tuned through the peak response point. The motor driving circuit, which is also shown in de-

tail in Fig. 14 of the drawings, is provided for the purpose of supplying control currents to the differential field windings of the D. C. driving motor 25 thereby to control the tuning of the circuit 15.

Referring now to Fig. 14, the control voltages from the starting circuit 42 are supplied over the conductors 52 and 52a to the movable contacts 333 and 334 of the reversing relay indicated generally at 335. The coil 336 of the reversing relay 335 is connected from the anode of a reversing tube 337 to the B+ supply. The reversing relay 335 is provided with a pair of fixed contacts 338 and 339 which are connected together and are further connected over the conductor 53a to the control grid of one motor driving tube 340, and with a second pair of fixed contacts 341 and 342 which are connected together and are connected over the conductor 53 to the control grid of the other motor driving tube 343. The control grid of the reversing tube 337 is connected to ground and the screen grid thereof is connected through a resistor 344 to the B+ supply. A reversing voltage from the reversing counter circuit of Fig. 15 is supplied over the conductor 55 and through the resistor 346 to the suppressor grid of the reversing tube 337. The reversing counter circuit 45 thus controls the conduction of the reversing tube 337 and hence the position of the reversing relay in a manner to be described in more detail in connection with Fig. 15.

The motor driving tubes 340 and 343 are of the pentode type and supply current of sufficient magnitude to the differential field windings of the driving motor 25 to cause movement of the tuning slug in the desired direction. Thus, the cathodes of the tubes 340 and 343 are connected together and are connected through a common cathode resistor 350 to ground potential. The anode of the motor driving tube 340 is connected through one field winding 351 of the motor 25 to the B+ supply and the anode of the tube 343 is connected through the other field winding 352 of the motor 25 to the B+ supply. The control grids of the tubes 340 and 343 are connected respectively through the condensers 345 and 347 to ground. The condensers 345 and 347 hold the grid potentials of the tubes 340 and 343 to a reasonable value during the open circuit periods when the reversing relay 335 switches over. In this connection it will be understood that the armature 353 of the driving motor 25 is energized by any suitable source of unidirectional potential, such as the power supply 46 shown in Fig. 1.

Considering now the second function performed by the starting circuit 42 upon closure of the starting switch 500, namely that of initially providing an independent control voltage for the motor driving circuit 44 so as to drive the tuning slug in the direction of the peak response point of the circuit 15, it will be understood that when the starting relay 316 (Fig. 13) is closed in the manner described above, the movable contacts 327 and 329 thereof respectively engage the fixed contacts 325 and 326 and a relatively positive potential is supplied from the junction of the resistors 322 and 323 through the contacts 326 and 329 and by way of the conductor 52 and the closed contacts 334 and 338 of the reversing relay 335 to the control grid of the motor driving tube 340. Also, a relatively negative potential is supplied from the junction point of the resistors 323 and 324 through the contacts 325 and 327 and by way of the conductor 52a and the closed contacts 333 and 342 of the reversing relay 335 to the control grid of the motor driving tube 343. The tube 340 draws a larger current than the tube 343 thus causing the armature of the driving motor 25 to rotate in a predetermined direction such that the tuning slug is moved toward the peak response point of the circuit 15.

The above-described independent control voltage is supplied to the motor driving circuit 44 until the starting relay 316 is de-energized. It will be recalled that the starting relay 316 is in turn controlled by the differential

relay 301 and accordingly the starting relay is not opened until the tuning slug has been moved sufficiently beyond the peak response point of the circuit 15 to provide a positive control voltage to the tube 297 which is sufficient to overcome the original unbalance provided by the cathode resistor 306. However, when the original internal unbalance of the differential relay circuit is overcome the differential relay 301 opens and the starting relay is de-energized so that the movable contacts 327 and 329 thereof are connected respectively through the fixed contacts 329 and 321 to the conductors 50 and 50a from the differential D. C. amplifier 34. With this arrangement the independent control voltage produced across the resistor 323 and supplied to the motor driving circuit 44 at the start of the alignment cycle is removed when the differential relay 301 opens and there is substituted therefor the balanced control voltages which are supplied from the differential D. C. amplifier 34 over the conductors 50 and 50a.

Inasmuch as the control voltage supplied over the conductor 50 must necessarily be positive with respect to its initial or reference value to overcome the unbalance due to the cathode resistor 306, as has been described in detail in connection with the differential relay circuit 35, it is seen that the polarity of the balanced control voltage supplied over the conductors 50 and 50a to the motor driving circuit in the manner described above is the same as the polarity of the independent control voltage initially supplied to the motor driving circuit so that the motor 25 would continue to rotate in the same direction and would move the tuning slug away from the desired peak response point. Accordingly, it is necessary to reverse the reversing relay 335 when the starting relay 316 is de-energized so as to reverse the polarity of the balanced control voltage supplied from the differential D. C. amplifier to the motor driving circuit 44 thereby to cause the tuning slug to move back to the desired peak response point. This reversal of the relay 335 is effected by the reversing counter circuit 45 which controls conduction of the reversing tube 337 so that the relay coil 336 of the reversing relay 335 is successively energized and de-energized each time the reversing counter circuit 45 is actuated. Assuming that the reversing tube 337 is initially conducting so that the contacts of the reversing relay 335 initially occupy the position shown in Fig. 14, when the balanced control voltage from the differential D. C. amplifier is substituted for the independent control voltage from the starting circuit 42 by operation of the differential relay 301 to de-energize the starting relay 316, the reversing counter circuit 45 is energized through the contacts 310 and 311 of the relay 301 over the conductor 51 and the tube 337 is rendered non-conductive. Accordingly, the movable contact 334 of the reversing relay 335 engages the fixed contact 341 and the movable contact 333 engages the fixed contact 339. It is thus evident that the polarity of the balanced control voltage supplied to the motor driving circuit 44 is reversed. Accordingly, the motor driving tube 343 now draws a larger current than the tube 340 and the driving motor is rotated in the opposite direction to move the tuning slug back toward the peak response point.

Reversing counter circuit 45

As discussed generally in connection with the general description of the system of Fig. 1, the reversing counter circuit 45 which is shown in detail in Fig. 15 of the drawings, is provided for the purpose of actuating the reversing relay circuit 43 each time the circuit 15 is tuned through the peak response point.

Referring to Fig. 15, the B+ control impulse which is produced in the differential relay circuit 35 each time the differential relay 301 closes in the direction to close the contacts 310 and 311, is supplied over the conductor 51 to a multivibrator indicated generally at 360. Thus, the control impulse from the differential relay circuit 35 is supplied over the conductor 51 and through the resistor 361

and the coupling condenser 362 to the control grid of one tube 363 of the multivibrator 360. The tube 363 is normally biased against conduction by means of the bias network including the resistors 364 and 365 which are connected between the negative supply $-V$ and ground. The anode of the tube 363 is coupled through the condenser 366 to the control grid of the other tube 367 of the multivibrator 360, and the anode of the tube 367 is back-coupled through the condenser 370 to the control grid of the tube 363. A triggering pulse is derived from the anode circuit of the tube 363 and is used to actuate an electronic switching circuit indicated generally at 386. Thus, a multivibrator output pulse from the anode of the tube 363 is coupled through the condensers 371 and 372 to the suppressor grid of the switching tube 373 and is also coupled through the condenser 374 to the suppressor grid of the switching tube 375. The switching tubes 373 and 375 are of the pentode type and the anode of each tube is interconnected with the control grid of the opposite tube so that the tubes are alternately switched from a conductive to a non-conductive state. The switching circuit 386 is substantially similar to the switching circuit 37 shown in Fig. 6 of the drawings, and accordingly, a detailed description thereof is considered unnecessary.

In order that the reversing counter circuit 45 may be set to a predetermined position at the start of the alignment cycle there is provided a diode tube 384, the anode of which is connected to the control grid of the switching tube 375 and the cathode of which is connected through the counter setting switch 385 to the negative supply $-V$. The control grid circuit of the switching tube 375 is utilized as a source of reversing voltage and the control grid potential is directly connected over the conductor 55 to the reversing tube 337 of the reversing relay circuit 43.

Considering now the operation of the above-described reversing counter circuit 45, when the contacts 310 and 311 of the differential relay 301 are closed, $B+$ potential is applied over the conductor 51 to the series connected resistors 361 and 361a and the flow of current through the resistor 361a produces a positive potential across this resistor which is coupled through the condenser 362 to the tube 363 and causes this tube to conduct thus triggering the multivibrator and initiating one multivibrator cycle. When the tube 363 is triggered into conduction, the voltage at the anode of the tube 363 decreases abruptly and remains at this potential until the tube 363 is cut off by the feed-back pulse supplied through the coupling condenser 370 from the tube 367, as will be readily apparent to those skilled in the art. There is thus produced in the anode circuit of the multivibrator 360 a single negative multivibrator pulse each time the contacts 310 and 311 of the differential relay 301 close. The negative multivibrator pulses are supplied to the suppressor grids of both the switching tubes 373 and 375 so that regardless of which switching tube is conducting the conducting tube is turned off. Accordingly, the switching circuit 386 acts as a two to one counter for closures of the differential relay 301 and the control grid potential of the switching tube 375 is successively raised and lowered in response to negative pulses from the multivibrator 360.

In order that the switching circuit 386 may be set to a predetermined position such that the reversing relay 335 is in the correct position at the start of the alignment cycle, the counter setting switch 385 is closed at the start of the alignment cycle so as to apply the full negative supply potential to the control grid of the switching tube 375 thereby insuring that the tube 375 is non-conductive at the start of the alignment cycle. The switch 385 is then opened and the switching circuit 386 is ready for the alignment cycle. When the switch 385 is opened, the potential at the control grid of the switching tube 375 remains at a relatively large negative potential until the application of a control pulse from the multivibrator 360. Accordingly, the reversing voltage supplied over the conductor 55 to the reversing tube 337 (Fig. 14) is negative,

the tube 337 is non-inductive and the reversing relay 335 occupies the position shown in Fig. 14.

When the tuning slug has been moved beyond the peak response point by an amount sufficient to cause the differential relay 301 to close in the opposite direction from its initial closure, the contacts 310 and 311 thereof are closed and a control pulse is supplied to the multivibrator 360 so as to cause a single cycle of operation thereof. The single multivibrator pulse thus produced is supplied to the switching circuit 386 and the switching tube 375 is rendered conductive. When the tube 375 is conductive, the control grid potential thereof increases positively and becomes approximately equal to ground potential. The reversing voltage supplied over the conductor 55 to the reversing tube 337 thus becomes more positive and the tube 337 conducts thereby causing current to flow through the reversing relay coil 336 and the reversing relay 335 is actuated to the opposite position from that shown in Fig. 14. It is thus evident that the closure of the contacts 310 and 311 of the differential relay 301 causes a reversal in the polarity of the balanced control voltages supplied to the motor driving circuit 44 so that the motor 25 is reversed from its original direction and the tuning slug is moved back toward the maximum response point of the circuit 15.

When the tuning slug has been moved back to the maximum response point, the balanced control voltages on the conductors 50 and 50a are equal, the differential relay 301 is balanced and hence the contacts 310 and 311 thereof are opened. Also, when the balanced control voltages on the conductors 50 and 50a are equal, the voltages supplied to the motor driving tubes 340 and 343 are equal thus causing equal current flow in the field windings 351 and 352 of the motor 25 and accordingly, the motor is stopped and the tuning slug is positioned at the desired maximum response point.

If the inertia of the driving system is substantial, the tuning slug overshoots the maximum response point of the circuit 15 so that the balanced control voltages on the conductors 50 and 50a are not equal but instead the control voltage on the conductor 50 is more positive and the voltage on the conductor 50a is more negative. In this connection it will be recalled that the memory circuit voltage is representative of the peak response of the circuit 15 so that the output from the comparison bridge 30 is positive with respect to its initial or reference value on both sides of the maximum response point. It will also be recalled that the balance control voltages on the conductors 50 and 50a are derived from the comparison bridge output and these voltages are used to control the movement of the tuning slug after the first reversal thereof. Accordingly, it is necessary to reverse the polarity of the balanced control voltages supplied over the conductors 50 and 50a to the motor driving circuit after each passage through the maximum response point. Such a reversal in the polarity of the voltage supplied over the conductors 50 and 50a to the motor driving circuit 44 is achieved by the above-described reversing counter circuit 45 which either opens or closes the reversing relay 335 for each closure of the contacts 310 and 311. Hence the reversing counter circuit operates to reverse the relay 335 and reverses the direction of movement of the tuning slug each time that the tuning slug is moved beyond the maximum response point by an amount sufficient to produce a positive unbalance of the control voltages on the conductors 50 and 50a which is of sufficient amplitude to cause the differential relay 301 to close. This sequence of events is continued until the tuning slug is accurately aligned to the maximum response point of the tunable circuit 15.

In order to correlate the operation of the differential relay circuit 35, the starting circuit 42, the reversing relay circuit 43, the motor driving circuit 44 and the reversing counter circuit 45 in effecting the above-described movement of the tuning slug, there is shown in Fig. 2c the current variations in the opposed coils 302 and 303 of

the differential relay 301 during the alignment cycle. Thus, referring to Fig. 2c, the current flowing through the coil 303 of the differential relay 301 is illustrated as the current I_1 , and the current flowing through the coil 302 of the relay 301 is illustrated as the current I_2 . In order to simplify the description of the differential relay circuit, the current I_1 is illustrated as having a fixed value throughout the alignment cycle. However, it will be understood that the current I_1 actually varies in the same manner as the current I_2 , although in the opposite direction, due to the push-pull nature of the balanced control voltages supplied over the conductors 50 and 50a to the differential relay circuit 35.

Upon closure of the starting switch 500 the current I_2 through the coil 302 of the differential relay 301 is decreased by an amount B due to the insertion of the resistor 306 in the cathode circuit of the tube 297 thus causing the differential relay 301 to close in the direction shown in Fig. 13 and to hold the starting relay 316 closed. The currents I_2 and I_1 remain in the above-described unbalanced condition until the point of maximum response is first reached at the time t_1 , after which the current I_2 gradually increases due to the increasing detector voltage as shown by the segment 62 of the response curve in Fig. 2a. In this connection it will be recalled that the differential relay circuit 35 is controlled in accordance with the output from the comparison bridge 30 and hence as the detector voltage 62 becomes positive with respect to the memory condenser voltage 72 the current in the differential relay windings 302 and 303 varies accordingly.

When the currents I_1 and I_2 are exactly equal, a condition illustrated as occurring at time t_2 , the differential relay 301 opens from its original position, the original unbalance is removed due to the short-circuiting of the resistor 306 and the current I_2 immediately becomes greater than the current I_1 by an amount B_1 which is equal to the original unbalance B. When the current I_2 increases by the amount B_1 the differential relay 301 is closed in the opposite direction so that the starting relay 316 is opened, the balanced control voltages on the conductors 50 and 50a are substituted for the independent control voltage across the resistor 323 of the starting circuit 42, and a control impulse is supplied to the reversing counter circuit 45 so as to reverse the direction of movement of the tuning slug and move it back toward the point of maximum response. The current I_2 thus decreases after the time t_2 until it is exactly equal to the current I_1 , which point occurs at the time t_3 , whereupon the differential relay 301 again opens. However, due to the overshoot of the mechanical drive system, the tuning slug is moved past the maximum response point so that the current I_2 again becomes greater than the current I_1 and the differential relay 301 again closes in the same direction. Upon closure of the differential relay in the same direction, another control impulse is supplied to the reversing counter circuit 45 and the reversing relay 335 is again reversed, a condition which is indicated as occurring at time t_4 , so that the tuning slug is driven back to the maximum response point. Reversal in the direction of movement of the tuning slug again causes the current I_2 to pass through coincidence with the current I_1 and causes a subsequent reversal in the direction of movement of the tuning slug as indicated at time t_5 . The direction of movement of the tuning slug is thus reversed as illustrated at t_2 , t_4 and t_5 to bring the circuit 15 into exact alignment with the frequency of the alignment signal applied thereto.

Coincidence memory system of Fig. 16

As discussed generally in connection with the general description of the alignment system of Fig. 1, there are several ways in which charging of the memory condenser 175 of the memory circuit 38 may be controlled. In the alignment system shown in Fig. 1 a sequential system of charging the memory condenser 175 is described in detail in connection with the memory circuit 38. However, it

will be recalled that the memory condenser may also be charged in accordance with a coincidence system. Such a coincidence memory system is shown in the alternative alignment system which is illustrated in block diagram form in Fig. 16 of the drawings.

Referring to Fig. 16, the alternative alignment system shown therein is substantially similar to the alignment system of Fig. 1 except for the addition of a cross-over detector and amplifier 57 and certain interconnections between the units of the memory system. In this connection it is pointed out that the motor control system including the units 32, 33, 34, 35, 42, 43, 44, 45 and 46 are identical with corresponding units in the alignment system of Fig. 1. Also, the standard oscillator 39 and the square wave generator 41 are identical with the corresponding units shown in Fig. 1.

In the coincidence memory system of Fig. 16 the switching circuit 37 is turned on by means of a negative signal supplied from the gating amplifier 36 over the conductor 27 in a manner entirely similar to that discussed in connection with the sequential memory system of Fig. 1. However, the switching circuit is not turned off sequentially but instead the switching circuit remains in the on position until the output from the chopping circuit 31 changes polarity and becomes a positive-going square wave. In order to provide a negative shut off pulse when the output from the chopping circuit 31 changes from a negative-going square wave to a positive-going square wave, there is provided in the coincidence memory system of Fig. 16 a cross-over detector and amplifier 57. The cross-over detector and amplifier 57 is supplied with a reference voltage from the chopping circuit 31 over the conductor 56a and is also supplied with the chopping circuit square wave over the conductor 56. The negative shut off pulse produced by the cross-over detector and amplifier 57 is supplied over the conductor 57a to the switching circuit 37 and is utilized to terminate the memory condenser charging interval.

The cross-over detector and amplifier 57 which is described generally above, is shown in detail in Fig. 17 of the drawings. Thus, referring to this figure, the square wave produced by the chopping circuit 31 is supplied over the conductor 56 and through the resistor 401 and the coupling condenser 402 to the control grid of an amplifier tube 403. The square wave for the cross-over detector and amplifier 57 may be derived from any suitable point in the chopping circuit 31. For example, the square wave which appears on the conductor 109 of the chopping circuit 31 (Fig. 4) may be connected over the conductor 56 to the cross-over detector and amplifier. A reference voltage is supplied from the chopping circuit 31 over the conductor 56a and through the crystal rectifier 411 to the junction point of the resistor 401 and the condenser 402. The reference voltage for the cross-over detector and amplifier 57 may be supplied from the arm of the potentiometer 105 (Fig. 4) and supplied over the conductor 56a in the manner described above. A by-pass condenser 407 may be connected from the cross-over detector end of the conductor 56a to ground so as to reduce pick-up on the conductor 56a extending from the chopping circuit 31 to the cross-over detector and amplifier 37.

The control grid of the amplifier tube 403 is normally biased negatively to approximately the mid-point of its operating characteristic by means of the network including the resistors 404, 405 and 406, the resistors 405 and 406 being connected between the negative source of potential $-V$ and ground. An output signal derived from the anode of the amplifier tube 403 is coupled through the condenser 413 to the control grid of a second amplifier tube 414. The tube 414 is normally operated at zero bias by connecting the grid resistor 408 thereof to the B_+ supply. An output signal derived from the anode of the amplifier tube 414 is coupled through the condenser 416 and the limiting resistor 417 to the control

grid of a third amplifier tube 418. The tube 418 is normally biased negatively by means of the network including the resistors 420, 421 and 422, the resistors 421 and 422 being connected between the negative source $-V$ and ground. The amplified signal produced across the anode resistor 419 of the tube 418 is coupled through the condenser 423 to the control grid of a cathode follower tube 424 and is repeated across the cathode resistor 424a of the tube 424. The signal produced across the cathode resistor 424a is then coupled through the condenser 425 to the control grid of a cathode follower output tube 426 and is repeated across the cathode output resistor 427. The negative signal appearing across the cathode resistor 427 is supplied over the conductor 57a to the input terminal 171 of the switching circuit 37 (Fig. 6) and through the differential network including the condenser 168 and the resistor 169 to the suppressor grid of the switching tube 157.

Considering now the operation of the above-described cross-over detector and amplifier 57 in the coincidence memory system of Fig. 16, it will be seen from the foregoing description that the reference voltage, which is supplied over the conductor 56a to the anode of the rectifier 411, functions to hold the anode of the rectifier 411 at a fixed potential which corresponds to the potential of the fixed contact 100 in the chopping circuit 31 (Fig. 4). In this connection it will be recalled that the potentiometer arm 105 is initially adjusted at the start of the alignment cycle so that the potential at the arm 105 is exactly equal to the initial output voltage from the comparison bridge 30. When the signal supplied from the chopping circuit 31 over the conductor 56 comprises a negative-going square wave, it will be seen that the rectifier 411 will conduct due to the fact that the negative-going square wave tends to reduce the potential of the cathode of the rectifier 411 below the anode potential thereof. Accordingly, the rectifier 411 conducts during a negative-going square wave and clamps the input circuit of the tube 403 to the reference potential on the conductor 56a.

When the memory circuit voltage exceeds the detector voltage the output from the chopping circuit 31 changes to a positive-going square wave. When a positive-going square wave is supplied over the conductor 56 to the cross-over detector and amplifier 57, the rectifier 411 is rendered non-conductive and the control grid of the tube 403 is driven positive. In this connection it will be recalled that the control grid of the tube 403 is normally biased negatively to permit the control grid to be driven positive as described above. There is thus produced a negative pulse across the anode load resistor 412 of the amplifier tube 403 which is coupled to the amplifier tube 411 wherein it is further amplified and repeated across the load resistor 415 of the tube 414 as a positive-going pulse. The positive-going pulse appearing at the anode of the tube 414 is coupled through the condenser 416 and the resistor 417 to the amplifier tube 418 wherein it is amplified and appears as a negative going pulse across the anode resistor 419 of the tube 418. The amplifier negative pulse produced across the resistor 419 is coupled through the cathode followers 424 and 426 and is supplied over the conductor 57a to the suppressor grid of the switching tube 57 of the switching circuit 37.

Charging of the memory condenser is thus terminated in response to the negative shut-off pulse produced on the output conductor 57a of the cross-over detector and amplifier 57 each time the memory circuit voltage supplied over the conductor 14 to the comparison bridge 30 exceeds the detector voltage supplied over the conductor 12 to the comparison bridge 30.

From the foregoing description it will be seen that under the coincidence charging system the memory condenser is charged aperiodically for the interval of time necessary to bring the memory circuit voltage up to the instantaneous detector voltage.

Contrasting now the operation of the sequential and coincidence memory systems and assuming that the detector voltage has been increased negatively by a given increment and a negative-going square wave is produced 5 from the chopping circuit 31, in the sequential system, the switching circuit 37 is turned on coincident with the leading edge of the negative-going square wave and is turned off coincident with the trailing edge of the square wave so that the memory circuit condenser is sequentially 10 charged in fixed equal increments until the memory circuit voltage is equal to the detector voltage at which time the output from the chopping circuit 31 becomes zero and the switching circuit is no longer turned on.

Still assuming that the detector voltage has been increased negatively by a given increment, in the coincidence 15 memory system the first negative square wave produced by the chopping circuit 31 is effective to turn on the switching circuit 37 and initiate charging of the memory condenser. However, the switching circuit is not turned off 20 coincident with the trailing edge of the negative-going square wave but instead the switching circuit remains on and the memory condenser 175 continues to be charged until the memory circuit voltage exactly equals the detector voltage at which time the cross-over detector and 25 amplifier 57 produces a negative shut-off pulse in the manner described above which is supplied to the switching circuit and turns off the switching circuit thus terminating the charging of the memory condenser.

From the foregoing description it will be evident that 30 the sensitivity of the coincidence memory system is limited only by the sensitivity of the gating amplifier 36 and the cross-over detector and amplifier 57. However, other delays in the memory system such as a delay in the output of the memory circuit 38 and in the input circuit to 35 the switching circuit 37, result in a delay of approximately 50 microseconds which is inherent in the system. This means that the memory circuit voltage will overshoot the detector voltage since the switching circuit will not be shut off at the required time and the memory condenser 40 will continue to charge for 50 microseconds after the peak response point is reached. The 50 microsecond delay interval has the effect of setting the minimum charging time for the memory condenser. If we assume that the charging current is linear with respect to time, which is approximately true for the small voltage to which the memory condenser is charged, an increase of 50 microseconds in charging time can be made to represent any desired portion of the charging period. For example, if an accuracy of .1 per cent is required, then 50 microseconds should 45 represent one part in 10,000 of the charging time (assuming a safety factor of ten), and the charging period would then be 500,000 microseconds or .5 second. If it is assumed that the gains of the gating amplifier 36 and the cross-over detector and amplifier 57 are such that these 50 units are not the limiting factors, a very small increment 55 of the detector voltage will start the operation of the memory system. This procedure will continue until the last increment is reached. It will then take the memory system 50 microseconds to shut off and in this period of time 60 the memory condenser will not charge by more than one part in 10,000. Accordingly, the error is set to a maximum of one part in 10,000.

In the coincidence memory system the total charging cycle must be contained within one of the on periods of 65 the chopping circuit square wave. This means that in the example given above, the on period will have to be at least .5 second and the square wave will have a frequency of one cycle per second. If the frequency of the standard square wave is too low, the balanced keyed rectifier 33 has 70 difficulty in integrating the square wave to produce unidirectional voltages inasmuch as the integration time constant of the balanced keyed rectifier circuit 33 should be at least ten times the frequency of the square wave. Accordingly, high speed operation of the system in the 75 example illustrated would be impossible. However, con-

sidering a practical chopping frequency of 60 cycles per second, the charging period is then a maximum of 8,333 microseconds. If the error time is still 50 microseconds then an accuracy of 50/8,333 or approximately 0.625 per cent is achieved. From the foregoing it is seen that the accuracy of the coincidence memory system is decreased as the frequency of the chopping circuit is increased due to the fact that the total charging cycle must be maintained within one of the periods of the chopping circuit square wave. It will be understood that the above accuracy does not take into account the inaccuracies of the remainder of the system. However, an accuracy of approximately four per cent may be expected with the coincidence memory system of Fig. 16 and a chopping frequency of 60 cycles per second.

Contrasting now the operation of the sequential memory system of Fig. 1 in the example given above, if the memory condenser is charged at regular intervals and an accuracy of one part in 10,000 is required, each charging period should allow the condenser to charge up by one of these 10,000 increments. Accordingly, there must be at least 10,000 off periods, or in other words, 10,000 cycles of the reference square wave during the memorizing process. If we assume that a total alignment cycle of one second is desired and the peak response point will be reached in one third of the total alignment time, i. e., in one third of a second, the chopping frequency must be three times 10,000, or 30,000 cycles per second. From the foregoing, it is seen that the square wave generator 41, which controls the frequency of the chopping circuit 31, should be of substantially higher frequency for the sequential memory system.

This is a considerably higher repetition rate than is feasible in the coincidence memory system of Fig. 16 and accordingly, the time constants associated with the balanced rectifier 33 may be considerably shorter. It is also seen that the time delay limitations in the sequential system of Fig. 1 are not so severe as in the coincidence of the system of Fig. 16 inasmuch as the cross-over amplifier and detector 57 is the main source of delay and this unit is not required in the sequential memory system.

ALTERNATIVE ALIGNMENT SYSTEM OF FIG. 18

In Fig. 18 of the drawings there is shown in block diagram form an alternative alignment system embodying the present invention wherein the alignment time is substantially decreased over the systems of Figs. 1 and 16 and wherein the accuracy of the alignment system is improved.

In general, the alternative alignment system of Fig. 18 aligns the tunable circuit 15 to its peak response point by first tuning the circuit through the peak response point to establish a memory voltage and thereafter tuning the circuit back to the peak response point under the control of the memorized reference voltage. In the alternative system of Fig. 18 certain units are identical with those employed in the system of Fig. 1, and the same reference numerals have been used to identify these units in both figures.

In order to control the tuning of the circuit 15 in such a manner that the circuit may be rapidly and accurately aligned to the desired peak response point, all D. C. amplification in the motor control portion of the alignment system is eliminated and the motor control circuits are A. C. coupled throughout. Accordingly, the stability of the motor control system is substantially increased due to the fact that D. C. amplification is not required for the relatively small changes in the detector voltage which occur close to the peak response point. A two-phase, 400 cycle motor 495 is used in the alternative system of Fig. 18 to rotate the tool 26 and hence to move the tuning slug 24 in and out of the inductive branch of the tuned circuit 15. With this arrangement the slot locking effects which are experienced with a split field D. C. motor are eliminated and the armature 498 of the 400 cycle driving

motor 495 is free accurately to assume any required angular position.

The A. C. motor control system of the alternative alignment system of Fig. 18 includes the comparison bridge 30, the chopping circuit 31, and the A. C. amplifier 32, all of which units are substantially identical with the corresponding units described in detail in the system of Fig. 1. In addition, the A. C. motor control system includes a phase reversal circuit 485, an A. C. motor driving circuit 490, an electronic starting circuit 465, a differential detector and amplifier 470, a counter circuit 475, and a time delay safety circuit 480. The comparison bridge 30, the chopping circuit 31, and the A. C. amplifier 32 perform functions substantially identical to those described in detail in connection with the system of Fig. 1, and accordingly, a detailed description thereof is considered unnecessary in connection with the alternative system of Fig. 18.

The phase reversal circuit 485 performs the function of converting the A. C. signal from the A. C. amplifier 32 into a pair of balanced alternating current voltages and of reversing the phase of the balanced alternating current voltages each time the circuit 15 is tuned through its peak response point. The phase reversal circuit 485 also performs the function of supplying a counter pulse to the counter circuit 475 each time the peak response point is passed. Also, the phase reversal circuit 485 introduces a 400 cycle unbalancing voltage of predetermined magnitude and phase at the start of the alignment cycle to start the motor 495 and tune the circuit 15 toward its peak response point. To perform these functions, the phase reversal circuit 485 is supplied with an A. C. signal from the A. C. amplifier 32 over the conductor 487 and supplies balanced driving voltages over the conductors 488 and 489 to the A. C. motor driving circuit 490. Also, the phase reversal circuit supplies a counter pulse over the conductor 486 to the counter circuit 475 and receives a control signal from the differential detector and amplifier 470 over the conductor 471 and a control signal from the electronic starting circuit 465 over the conductor 469.

The A. C. motor driving circuit 490 performs the function of supplying an alternating current to one phase winding 496 of the A. C. driving motor 495 in response to the balanced driving voltages supplied thereto from the phase reversal circuit 485. To perform this function the output of the A. C. motor driving circuit is connected over the conductors 491 and 492 to the winding 496 of the motor 495. The other winding 497 of the driving motor 495 is energized continually from the 400 cycle generator 460 over the conductor 461.

The electronic starting circuit 465 performs the functions of resetting the memory circuit 38a and the counter circuit 475 at the start of the alignment cycle, and supplies a 400 cycle unbalancing voltage of predetermined magnitude and phase to the phase reversal circuit 485 at the start of the alignment cycle to cause the motor 495 to tune the circuit 15 in the proper direction. The electronic starting circuit 465 also performs the function of controlling the time delay safety circuit 480. To reset the memory circuit 38a the electronic starting circuit 465 supplies a control signal over the conductor 466 to this unit. To reset the counter circuit 475 and start the time delay safety circuit 480 the electronic starting circuit supplies a control signal over the conductor 468 to these units. To turn off the safety circuit 480, the electronic starting circuit supplies a control signal over the conductor 467. The 400 cycle generator 460 supplies a 400 cycle unbalancing voltage to the electronic starting circuit 465 over the conductor 461 and at the start of the alignment cycle the 400 cycle unbalancing voltage is supplied from the electronic starting circuit 465 to the phase reversal circuit 485 over the conductor 469. The 400 cycle unbalancing voltage is removed by means of a control signal which is supplied to the electronic starting

circuit 465 over the conductor 471 from the differential detector and amplifier 470.

The differential detector and amplifier 470 performs the function of providing a control signal once the peak response point is first passed which control signal is used to reset the electronic starting circuit 465 and remove the 400 cycle unbalancing voltage from the phase reversal circuit 485. Thereafter the differential detector and amplifier 470 performs the function of reversing the phase of the balanced driving voltages produced by the phase reversal circuit 485 by supplying a control pulse over the conductor 471 to the phase reversal circuit 485 each time the peak response point is traversed. To derive the above-described control pulse the square wave output from the chopping circuit 31 is supplied over the conductor 20 to the input circuit of the differential detector and amplifier 470.

The counter circuit 475 performs the function of stopping the motor 495 after the circuit 15 has been tuned through its peak response point a predetermined number of times. To perform this function, the counter circuit is supplied with counter pulses from the phase reversal circuit 485 over the conductor 486 each time the peak response point is passed and the counter circuit supplies a blocking voltage over the conductor 476 to the A. C. amplifier 32 after a predetermined number of passages through the peak response point.

The time delay safety circuit 480 is provided for the purpose of preventing damage to the tuned circuit 15 and the motor driving equipment in the event that the receiver 10 is incorrectly wired and a peak response point is not experienced. To accomplish this function the time delay safety circuit 480 supplies a blocking pulse over the conductor 481 to the A. C. amplifier 32 a predetermined time interval after the start of the alignment cycle in the event that no peak response point is reached and thus stops the driving motor 495 before the tuning slug is jammed against the end of the coil 16.

In general, the memory system of the alternative alignment system of Fig. 18 is of the sequential type described in detail in connection with Figs. 1 and 7 and includes the comparison bridge 30, a 30 kilocycle chopping circuit 450, the gating amplifier 36, the switching circuit 37, and a modified memory circuit 38a. The comparison bridge 30, the gating amplifier 36 and the switching circuit 37 are identical with the corresponding units of the system of Fig. 1, and, accordingly, a detailed description thereof is considered unnecessary in connection with Fig. 18. However, due to the fact that the motor control portion of the alignment system of Fig. 18 is A. C. coupled throughout, it is necessary completely to separate the memory system from the motor control system. Accordingly, a separate 30 kilocycle chopping circuit 450 is provided and performs the function of deriving a 30 kilocycle square wave from the comparison bridge 30 which square wave is of the same amplitude and sense as the comparison bridge output. To perform this function, the comparison bridge output voltage is supplied over the conductor 13 to the 30 kilocycle chopping circuit 450 and a reference voltage from the chopping circuit 31 is supplied over the conductor 451 to the 30 kilocycle chopping circuit. Also, a 30 kilocycle square wave generator 455 is provided for the purpose of supplying positive and negative 30 kilocycle gating voltages over the conductors 456 and 457 to the 30 kilocycle chopping circuit 450. The memory circuit 38a of the system of Fig. 18 is identical with the memory circuit 38 of Fig. 1 with the exception that an additional circuit is provided for automatically discharging the memory condenser 175 at the start of each alignment cycle. In other respects the memory circuit 38a is entirely similar to the memory circuit 38 discussed in detail in connection with Figs. 1 and 7 and supplies a memory circuit voltage over the conductor 14 to the comparison bridge 30.

OPERATION OF THE ALTERNATIVE SYSTEM OF FIG. 18 AS A WHOLE

Briefly to consider the general mode of operation of the alternative system of Fig. 18 described above, the alignment cycle is started by closing the starting switch 500. When the switch 500 is closed a control signal is supplied from the electronic starting circuit 465 over the conductor 466 to the memory circuit 38a to reset the memory storage condenser 175. Also a control signal is supplied over the conductor 468 to the counter circuit 475 to reset this circuit and to the time delay safety circuit 480 to start the time delay interval thereof. Likewise the electronic starting circuit 465 supplies a 400 cycle unbalancing voltage over the conductor 469 to the phase reversal circuit 485 so that the driving voltages supplied by the phase reversal circuit 485 to the motor driving circuit 490 are unbalanced and the motor 495 tunes the circuit 15 toward its peak response point. In this connection it will be understood that the magnitude of the 400 cycle unbalancing voltage is substantially larger than any signal which may be supplied from the A. C. amplifier 32 so that the unbalancing signal overrides the normal signal supplied to the phase reversal circuit and tuning of the circuit 15 in the correct direction is insured.

As the resonant frequency of the circuit 15 is varied in the manner described above, the detector voltage on the conductor 12 becomes increasingly negative. The 30 kilocycle chopping circuit 450 converts the D. C. output from the comparison bridge 30 into a square wave of corresponding amplitude and sense, and the remaining units of the memory system function in the manner described in detail in connection with the system of Fig. 1 to provide a memory circuit voltage on the conductor 14 which follows the negatively increasing detector voltage and which is equal to the peak detector voltage after the peak response point is passed. After the peak response point is passed the detector voltage becomes less negative whereas the memory circuit voltage remains constant so that the output from the comparison bridge becomes positive with respect to its initial value and the output from the chopping circuit 31 becomes a positive-going square wave which is supplied over the conductor 20 to the differential detector and amplifier 470. When the chopping circuit square wave reverses polarity and becomes a positive-going square wave the differential detector and amplifier 470 produces a control pulse which is supplied over the conductor 471 to the electronic starting circuit 465 and the phase reversal circuit 485. The differential detector control pulse is effective to remove the 400 cycle unbalancing voltage from the phase reversal circuit 485 and the phase reversal circuit is thereafter controlled solely by the output from the A. C. amplifier 32. Also, the differential detector control pulse is supplied directly to the phase reversal circuit over the conductor 471 and effects reversal of the balanced driving voltages on the conductor 488 and 489 so that the driving motor 495 is reversed after the peak response point is passed. From the foregoing, it is evident that the motor 495 is reversed a predetermined time interval after the peak response point is first passed as determined by the time required to develop the differential detector control pulse and reverse the balanced driving voltages from the phase reversal circuit 485.

When the 400 cycle unbalancing voltage is removed from the phase reversal circuit this circuit is controlled solely by the output from the comparison bridge 30 which output is converted into an A. C. signal in the chopping circuit 31 and is amplified in the A. C. amplifier 32. After the motor 495 has been reversed and the tuning slug moved back to the peak response point, the output from the comparison bridge 30 falls to zero and the driving voltages on the conductors 488 and 489 are exactly balanced so that no voltage is supplied to the winding 496 of the motor 495 and the motor stops.

If the motor drive system possesses substantial inertia, the tuning slug may overshoot the peak response point and, when this happens, the output from the comparison bridge 30 again becomes positive and the differential detector and amplifier 470 develops another control pulse which is supplied to the phase reversal circuit and reverses the phase of the balanced driving voltages on the conductors 488 and 489 so that the motor 495 is again reversed and drives the tuning slug back to the peak response point. The above-described series of events is repeated until the tuning slug is stopped sufficiently close to the peak response point that the output from the comparison bridge 30 is insufficient to develop another control pulse from the differential detector and amplifier 470 at which time the alignment cycle is completed.

Inasmuch as the circuit 15 is tuned close enough to the desired peak response point after a few reversals in the direction of tuning thereof, the alignment cycle may be terminated by employing the counter circuit 475 which de-energizes the driving motor 495 after the circuit 15 has been tuned through its peak response point a predetermined number of times. To accomplish this, each time the phase of the balanced driving voltages from the phase reversal circuit 485 is reversed, a control pulse is supplied over the conductor 486 to the counter circuit 475 and after a predetermined number of pulses are supplied over the conductor 486 a blocking signal is supplied over the conductor 476 to the A. C. amplifier so as completely to block the passage of signals through the A. C. amplifier thereby removing voltage from the motor winding 496 and stopping the motor 495.

In the event that the motor drives the tuning slug through the coil 16 without passing through a peak response point, a condition which may readily occur if the resonant circuit 15 is incorrectly wired, it is necessary to stop the motor 495 before it overshoots the tuning slug and damages the coil 16, for which purpose the time delay safety circuit 480 is provided. The time delay of the circuit 480 is initiated by means of a control signal which is supplied over the conductor 468 from the electronic starting circuit at the start of the alignment cycle. If no peak response point is encountered, the differential detector and amplifier 470 does not develop a control pulse and the electronic starting circuit 465 is not reset to its original position. If the electronic starting circuit 465 is not reset to its original position within a predetermined time interval after the start of the alignment cycle, the time delay safety circuit develops a blocking pulse which is supplied over the conductor 481 to the A. C. amplifier 32 and blocks the transmission of signals through this amplifier so that the motor 495 is stopped. However, if a peak response point is reached and the differential detector and amplifier 470 develops a control pulse, the electronic starting circuit is reset to its original position and a control signal is supplied over the conductor 467 from the electronic starting circuit to the time delay safety circuit 480 so that the time delay-safety circuit is disabled and can not supply a blocking pulse to stop the motor 495. The alignment cycle then proceeds in a normal manner.

30 kilocycle chopping circuit 450

As discussed generally in connection with the general description of the alternative system of Fig. 18, the 30 kilocycle chopping circuit 450, which is shown in detail in Fig. 19 of the drawings, is provided for the purpose of converting the output from the comparison bridge 30 into a 30 kilocycle square wave of corresponding amplitude and sense. In this connection it will be understood that the chopping circuit 31 performs a generally similar function and provides a 400 cycle square wave having an amplitude and sense corresponding to the output from the comparison bridge for the motor control portion of the system. Inasmuch as the memory sys-

tem employed in the system of Fig. 18 is of the sequential type and a 30 kilocycle chopping rate is employed, a chopping circuit similar to the chopping circuit 31 is not employed in the memory system of Fig. 18. This is because the circuit 31 is inherently a low frequency device, and the mechanical movement of the vibratory system limits the chopping circuit 31 to a relatively low frequency of operation. Accordingly, the 30 kilocycle chopping circuit 450 is electronic and is supplied with positive and negative square waves from the 30 kilocycle square wave generator 455 over the conductors 456 and 457.

In order to convert the gradually varying output from the comparison bridge into a square wave of corresponding amplitude and sense, the output voltage from the comparison bridge 30 is supplied over the conductor 13 to the cathode of a first crystal rectifier 504. The anode of the crystal rectifier 504 is connected to the cathode of a second crystal rectifier 501, the anode of the rectifier 501 being connected to ground. In a similar manner the unidirectional reference voltage produced at the arm of the potentiometer 106 in the chopping circuit 31 (Fig. 4) is supplied over the conductor 451 to the cathode of a third crystal rectifier 502. The anode of the rectifier 502 is connected to the cathode of a fourth crystal rectifier 503, the anode of the rectifier 503 being connected to ground. The cathodes of the rectifiers 501 and 503 are connected together through the series resistors 505 and 506, which are preferably of equal value as will be described in more detail hereinafter, and an output voltage square wave is derived from the junction point of the resistors 505 and 506 and is supplied through the series resistors 507 and 508 and over the output conductor 452 to the gating amplifier 36. In order to filter the square wave derived at the junction point of the resistors 505 and 506, there is provided the shunt condensers 509 and 510 which are connected from either side of the resistor 508 to ground potential.

The positive gating square wave is supplied from the 30 kilocycle square wave generator 455 over the conductor 456 and through the resistor 515 to the common connection of the rectifiers 504 and 501 and the resistor 505. Also, the negative gating square wave from the square wave generator 455 is supplied over the conductor 457 and through the resistor 516 to the common connection of the rectifiers 502 and 503 and the resistor 506.

Considering now the operation of the 30 kilocycle chopping circuit 450, it will be recalled that the comparison bridge output voltage which is supplied over the conductor 13 comprises a variable unidirectional voltage which varies in accordance with the difference between the detector voltage from the receiver 10 and the memory circuit voltage from the memory circuit 38a. Also, the reference voltage which is supplied over the conductor 451 from the chopping circuit 31 comprises a fixed unidirectional voltage which is adjusted at the start of the alignment cycle so that it is equal to the initial value of the comparison bridge output on the conductor 13. Thus, at the start of the alignment cycle the unidirectional voltages on the conductors 13 and 451 are equal. The positive-going portion of the positive gating wave supplied over the conductor 456 is clamped to the potential of the conductor 13 by conduction of the rectifier 504. This is readily apparent when it is realized that as the anode of the rectifier 504 becomes positive during the positive portion of the gating wave on the conductor 456, a point will be reached at which the anode potential of the rectifier 504 is greater than the cathode potential thereof, i. e., the potential on the conductor 13 and the rectifier 504 will conduct and clamp the gating wave to the potential of the conductor 13. Also, the negative-going portion of the positive gating wave supplied over the conductor 456 is clamped to ground potential by conduction of the rectifier 501. Thus, as the cathode of the rectifier

501 becomes more negative during the negative portion of the gating wave on the conductor 456, a point is reached at which the cathode potential of the rectifier 501 is more negative than the anode thereof and the rectifier 501 conducts and clamps the gating wave to ground potential. The gating wave on the conductor 456 is thus converted by the action of the rectifiers 504 and 501 into a square wave having a fixed negative value at ground potential and having a variable amplitude or positive value depending upon the potential on the conductor 13 so that a variable amplitude positive square wave is produced at the common connection of the rectifiers 504 and 501 which varies in accordance with the potential on the conductor 13.

In a manner entirely similar to that described above, the fixed reference potential on the conductor 451 is employed to set the amplitude of the negative gating wave supplied over the conductor 457 and there is provided at the common connection of the rectifiers 502 and 503 a fixed amplitude negative square wave the negative value of which is clamped to ground potential and the positive value of which is clamped to the potential on the conductor 451.

The variable amplitude positive square wave derived from the gating wave supplied over the conductor 456 and the fixed amplitude negative square wave derived from the negative gating wave supplied over the conductor 457 are connected together through the series resistors 505 and 506. If the positive and negative square waves supplied to the outer ends of the resistors 505 and 506 are of equal amplitude and these resistors are of equal value, the potential at the midpoint of the resistors 505 and 506 remains constant as the potentials at the outer ends of these resistors vary in opposite directions and with equal amplitudes. However, when the potential on the conductor 13 becomes negative with respect to the potential on the conductor 451 the amplitude of the positive square wave is decreased so that the midpoint potential no longer remains constant but instead becomes negative during the positive portions of the reduced amplitude positive square wave. A negative 30 kilocycle square wave is thus produced at the midpoint of the resistors 505 and 506 when the potential on the conductor 13 becomes negative. Similarly, when the potential on the conductor 13 becomes positive with respect to the potential on the conductor 451 the amplitude of the positive square wave increases so that the midpoint potential becomes positive during the positive portions of the increased amplitude positive square wave and a positive 30 kilocycle square wave is produced at the midpoint of resistors 505 and 506.

From the foregoing, it is seen that the output square wave produced by the 30 kilocycle chopping circuit 450 has an amplitude and sense corresponding to the potential on the conductor 13. The output square wave is filtered in the two section filter including the resistors 507 and 508 and the condensers 509 and 510, and the resulting sine wave is supplied over the conductor 452 to the gating amplifier 36. The gating amplifier 36, the switching circuit 37 and the memory circuit 38a cooperate in the manner described in connection with the system of Fig. 1 to provide a memory circuit voltage on the conductor 14 which is supplied to the comparison bridge to complete the loop circuit of the sequential memory system.

Memory circuit 38a

While the memory circuit 38a, which is shown in detail in Fig. 20 of the drawings, functions in a manner entirely similar to the memory circuit 38 of Fig. 1 during the alignment cycle, there is additionally provided in the memory circuit 38a means for automatically resetting the memory condenser 175 at the start of the alignment cycle. Thus, referring to Fig. 20, certain elements of the memory circuit 38a have been given reference numerals identical with the corresponding elements in the memory circuit 38. As will be recalled from the description of the memory circuit 38, the memory condenser 175 is

charged sequentially during the on periods of the controlling square wave and during the periods when the detector voltage is increasing negatively so that the condenser 175 assumes a charge of the polarity shown in Fig. 20. When the peak response point is reached, the memory condenser 175 has been charged to a negative voltage representative of the peak response point of the circuit 15 and holds this charge for the remainder of the alignment cycle.

In order to discharge the memory condenser 175 at the start of the alignment cycle, there is provided in the memory circuit 38a a diode rectifier 520, the cathode of which is connected to the negative plate of the condenser 175 and the anode of which is supplied with a control signal from the electronic starting circuit 465 over the conductor 466. The control signal supplied over the conductor 466 has a value equal to the negative supply potential $-V$ during the alignment cycle so that the anode potential of the rectifier 520 is below the cathode potential thereof, the rectifier 520 does not conduct and the memory condenser 175 is charged in the manner described in detail in connection with the memory circuit 38. However, when the next succeeding alignment cycle is initiated and the starting switch 500 is closed, the control signal supplied over the conductor 466 increases positively so that the anode of the rectifier 520 becomes positive with respect to the cathode and the rectifier 520 conducts. When the rectifier 520 conducts the memory condenser 175 is discharged through the series path including the resistors 182 and 183, the control signal source in the electronic starting circuit 465 which is connected to ground, and the rectifier 520 so that the memory condenser 175 is completely discharged immediately the alignment cycle is started. The control signal supplied over the conductor 466 is automatically changed when the starting switch 500 is depressed so that the memory condenser is automatically reset at the start of each alignment cycle.

Phase reversal circuit 485

Considering now the A. C. motor control portion of the alternative system of Fig. 18, it will be recalled that the A. C. driving motor 495 is first supplied with a 400 cycle unbalancing voltage at the start of the alignment cycle to tune the circuit 15 through the peak response point, and, after the peak response point is passed, the 400 cycle unbalancing voltage is removed and the motor 495 is controlled in accordance with the output from the comparison bridge to return the circuit 15 to the desired peak response point. The output from the comparison bridge is converted into a 400 cycle square wave in the chopping circuit 31 and the 400 cycle output from the chopping circuit 31 is amplified in the A. C. amplifier 32. In order to reverse the motor 495 each time the circuit 15 has passed through the peak response point, there is provided the phase reversal circuit 485 which is shown in detail in Fig. 21 of the drawings. The phase reversal circuit 485 also performs the function of introducing the 400 cycle unbalancing voltage into the A. C. motor control system at the start of the alignment cycle and also supplies a counter pulse to the counter circuit 475, each time the phase of the motor driving voltage is reversed.

Referring now to Fig. 21, the 400 cycle error signal from the A. C. amplifier 32 is supplied over the conductor 487 and through the coupling condenser 525 to a first phase inverter tube 526. The 400 cycle signal on the conductor 487 is also supplied through the condenser 525 to the control grid of a second phase inverter tube 527. The 400 cycle signal on the conductor 487 is repeated in like phase across the cathode resistor 528 of the phase inverter tube 526 and is also repeated in like phase across the cathode resistor 529 of the phase inverter tube 527. Also, the 400 cycle signal on the conductor 487 is repeated in opposite phase across the anode load

resistors 530 and 531 respectively of the phase inverter tubes 526 and 527. The in-phase output signal derived at the cathode of the phase inverter tube 526 is supplied through a coupling condenser 532 to the control grid of an electron discharge tube 533. The out-of-phase output signal derived at the anode of the phase inverter tube 527 is coupled through the condenser 534 to the control grid of an electron discharge tube 535. The anodes of the tube 533 and 535 are connected through the common load resistor 536 to the B+ supply and the cathodes of the tubes 533 and 535 are connected together and through the common cathode resistor 537 to ground. In a similar manner, the in-phase output signal derived at the cathode of the phase inverter tube 527 is coupled through the condenser 531 to the control grid of an electron discharge tube 538, and the out-of-phase output signal derived at the anode of the phase inverter tube 526 is coupled through the condenser 539 to the control grid of an electron discharge tube 540. The anodes of the tubes 538 and 540 are connected together and through the common anode resistor 541 to the B+ supply. The output voltages derived across the resistors 536 and 541 are supplied over the conductors 488 and 489 to the A. C. motor driving circuit 490 to provide a push-pull alternating current motor driving voltage which is suitable for excitation of the winding 496 of the driving motor 495.

From the foregoing, it is seen that the 400 cycle signal on the conductor 487 is supplied to both of the phase inverter tubes 526 and 527. The in-phase output signal from one phase inverter tube is combined with the out-of-phase output signal from the other phase inverter tube and vice versa, and the combined signals are reproduced across the anode resistors 536 and 541. If both of the phase inverter tubes 526 and 527 are conducting at the same time, it is evident that the in-phase and out-of-phase signals supplied to the control grids of the tubes 533, 535, 538 and 540 would exactly balance each other so that no voltage would be produced across the common anode resistors 536 and 541. However, the phase inverters 526 and 527 are controlled by means of a phase reversal switching circuit 550 so that only one of the phase inverters 526 or 527 is conducting at a given time.

The phase reversal switching circuit 550 is of the modified Eccles-Jordan type, and is generally similar to the electronic switching circuit 37, which has been discussed in detail in connection with Fig. 6 of the drawings. Considered generally, the phase reversal switching circuit 550 comprises a pair of electron discharge tubes 551 and 552, the anode and control grid circuits of which are interconnected so that the tubes are abruptly switched from a conductive to a non-conductive state in response to negative control pulses supplied to the suppressor grids of the tubes 551 and 552.

In order to control conduction of the phase inverter tubes 526 and 527 so that only one of these tubes is turned on at a given time, the suppressor grid of the phase inverter tube 526 is directly connected to the first control grid of the switching tube 551 and the suppressor grid of the phase inverter tube 527 is directly connected to the first control grid of the switching tube 552. The suppressor grids of the switching tubes 551 and 552 are directly connected together and are supplied with a negative control pulse from the differential detector and amplifier 470 over the conductor 471 each time the peak response point of the circuit 15 is traversed.

At the start of the alignment cycle a 400 cycle unbalancing voltage is supplied from the electronic starting circuit 465 over the conductor 469 and through the coupling condenser 550 to the control grid of the tube 538. The 400 cycle unbalancing voltage is of sufficient magnitude to override any signal which may be supplied to the control grids of the tubes 538 and 540 from the phase inverters 526 and 527 and the 400 cycle unbalancing volt-

age is of the correct phase to cause the motor 495 to rotate in a direction to tune the circuit 15 toward its peak response point. From the time the starting switch 500 is closed until the peak response point is reached, the 400 cycle unbalancing voltage is supplied over the conductor 469 to the tube 538, is amplified in this tube, and is supplied over the conductor 489 to the A. C. motor driving circuit 490 so as to drive the motor 495 in the correct direction. After the peak response point is reached, the 400 cycle unbalancing voltage is removed from the conductor 469 by the operation of the electronic starting circuit 465 so that the only voltage available to control the motor 495 is the 400 cycle signal supplied over the conductor 487 from the A. C. amplifier 32 to the phase reversal circuit 485.

When the peak response point is passed, the differential detector and amplifier 470 produces a negative control pulse which is supplied over the conductor 471 to the suppressor grids of the phase reversal switching tubes 551 and 552 and the phase reversal switching circuit 550 is reversed. Assuming that the phase inverter tube 527 is rendered conductive upon the first passage through the peak response point by the above-described reversal of the phase reversal switching circuit 550, it will be seen that with the tube 527 conducting an in-phase signal is supplied from the cathode of the phase inverter tube 527 to the tube 538, is repeated across the output resistor 541, and is supplied over the conductor 489 to the motor driving circuit 490. Also, the out-of-phase signal produced at the anode of the phase inverter tube 527 is supplied to the tube 535, is repeated across the resistor 536, and is supplied over the conductor 488 to the motor driving circuit 490. The output voltages thus produced across the resistors 536 and 541 are balanced push-pull voltages and have an amplitude proportional to the 400 cycle error signal supplied over the conductor 487 from the A. C. amplifier 32. Accordingly, the push-pull driving voltages produced on the conductors 488 and 489 operate to drive the motor back to the peak response point, and, as the peak response point is approached, the error signal from the comparison bridge decreases and the balanced push-pull voltages on the conductors 488 and 489 decrease correspondingly. When the circuit 15 is returned exactly to the peak response point the 400 cycle error signal on the conductor 487 falls to zero and the motor 495 is stopped. However, if the motor overdrives the peak response point a 400 cycle error signal again appears on the conductor 487 and if the phase of the balanced push-pull voltages on the conductors 488 and 489 is not reversed, this error signal would continue to drive the motor 495 in the same direction and away from the peak response point. To prevent this, as the peak response point is traversed, the differential detector and amplifier 470 produces another negative control pulse which is supplied over the conductor 471 to the phase reversal switching circuit 550 and reverses this switching circuit so that the phase inverter tube 527 is rendered non-conductive and the phase inverter tube 526 is conducting. With the phase inverter tube 526 conducting, the in-phase output signal at the cathode of the tube 526 is supplied to the tube 533 and the out-of-phase output signal at the anode of the tube 526 is supplied to the tube 540. It is thus seen that the phase of the balanced push-pull voltages repeated across the resistors 536 and 541 and supplied over the conductors 488 and 489 is reversed each time the phase reversal switching circuit 550 is actuated.

Each time the phase reversal switching circuit 550 is actuated a counter signal is supplied from the control grid of the switching tube 552 and over the conductor 486 to the countercircuit 475 so that the alignment cycle may be terminated after a predetermined number of passages through the desired peak response point, as will

be described in more detail in connection with the countercircuit 475.

A. C. motor driving circuit 490

As discussed generally in connection with the general description of the alternative system of Fig. 18, the A. C. motor driving circuit 490, which is shown in detail in Fig. 22 of the drawings, performs the function of energizing the A. C. driving motor 495 in accordance with the push-pull motor control voltages produced by the phase reversal circuit 485.

Thus, referring to Fig. 22, the push-pull motor control voltages are supplied over the conductors 488 and 489 to the control grids of the motor control tubes 560 and 561. The anodes of the motor control tubes 560 and 561 are connected together and are connected through the common anode resistor 562 to the B+ supply. The cathode of the driving tube 560 is connected to one end of the primary winding 563 of an output transformer 564 and the cathode of the driving tube 561 is connected to the other end of the winding 563. The center tap 565 of the winding 563 is connected through the resistor 566 to ground. The motor driving voltage produced across the secondary winding 567 of the output transformer 564 is supplied over the conductors 491 and 492 to one winding 496 of the driving motor 495. The other winding 497 of the split phase motor 495 is supplied with a 400 cycle signal of fixed amplitude and phase from the 400 cycle generator 460 over the conductor 461.

The push-pull voltages appearing on the conductors 488 and 489 are coupled through the motor driving tubes 560 and 561 to the primary winding 563 and appear as a single ended motor driving voltage across the secondary winding 567. As the voltage across the winding 567 decreases, the speed of the motor 495 decreases and when the voltage across the winding 567 is equal to zero the motor 495 is stopped. When the polarity of the balanced push-pull voltages on the conductors 488 and 489 is reversed, the output driving voltage across the winding 567 is reversed and the motor 495 reverses direction. Accordingly, the motor 495 is controlled by the phase reversal circuit 485 to align the circuit 15 to the desired peak response point in the manner described in detail above.

Electronic starting circuit 465

As discussed generally in connection with the general description of the alternative system of Fig. 18, the electronic starting circuit 465, which is shown in detail in Fig. 23 of the drawings, performs the functions of resetting the memory circuit 38a and the countercircuit 475 at the start of the alignment cycle, supplying a 400 cycle unbalancing voltage of predetermined magnitude and phase to the phase reversal circuit 485 at the start of the alignment cycle and of controlling the time delay safety circuit 480 in such a manner that the time delay safety circuit 480 does not block the A. C. amplifier 32 if a peak response point is reached within a normal interval of time.

Referring now to Fig. 23 of the drawings, the starting switch 500 is closed to initiate the alignment cycle. When the switch 500 is closed, a circuit is completed from the negative supply potential -V through the resistors 575 and 576 to ground potential. In order to reset the memory condenser 175 of the memory circuit 38a, the voltage across the resistor 575 is utilized as a control signal and is supplied over the conductor 466 to the resetting diode 520 discussed in detail in connection with Fig. 20. When the switch 500 is open, there is no current flow through the resistor 575 and the voltage on the conductor 466 is equal to the negative supply potential -V. However, when the switch 500 is closed at the start of the alignment cycle, the flow of current through the resistor 575 to the negative supply potential raises the

potential on the conductor 466 by an amount determined by the resistance values of the resistors 575 and 576. The amount by which the potential on the conductor 466 is raised when the switch 500 is closed is so chosen that it is sufficient to cause the resetting diode 520 to conduct and thereby discharge the memory condenser at the start of the alignment cycle.

When the alignment cycle is started, the electronic starting circuit 465 also resets the counter circuit 475. To accomplish this, the voltage across the resistor 576 is supplied over the conductor 468 to the counter circuit 475. It will be seen that during the alignment cycle, i. e., when the switch 500 is open, the voltage across the resistor 576 is equal to zero and accordingly, the conductor 468 is at ground potential. However, when the switch 500 is closed, at the start of an alignment cycle, a negative voltage drop is produced across the resistor 576 and the potential to the conductor 468 decreases to a negative potential as determined by the relative values of the resistors 575 and 576. The negative signal thus produced on the conductor 468 is utilized in the counter circuit 475 to reset this circuit in a manner to be described in more detail in connection with the detailed description of the circuit 475.

A 400 cycle signal is supplied from the 400 cycle generator 460 over the conductor 461 and through a coupling condenser 580 to the suppressor grid of a starting control tube 581. When the tube 581 is conducting, the 400 cycle signal is repeated across the anode load resistor 582 of the tube 581 and is supplied through the coupling condenser 583 and over the conductor 469 to the phase reversal circuit 485. Conduction of the starting control tube 581 is controlled by a starting control switching circuit indicated generally at 590, which is of the modified Eccles-Jordan type, and, in general, is similar to the electronic switching circuit 37 discussed in detail in connection with Fig. 6 of the drawings. Generally considered, the starting control switching circuit 590 comprises a pair of electron discharge tubes 591 and 592, the anode and control grid circuits of which are interconnected so that the tubes are switched abruptly from a conductive to a non-conductive state in response to negative control pulses supplied to the suppressor grids of the tubes 591 and 592. The suppressor grid of the switching tube 591 is connected to the ungrounded side of the resistor 576 so that the switching tube 591 is controlled in accordance with the negative voltage produced across the resistor 576 when the switch 500 is closed at the start of the alignment cycle. The switching tube 592 is controlled in accordance with the negative control pulses which are produced by the differential detector and amplifier 470 and are supplied over the conductor 471 and through the coupling condenser 585 to the suppressor grid of the switching tube 592.

Considering now the manner in which the electronic starting circuit 465 functions initially to apply the 400 cycle unbalancing voltage to the phase reversal circuit 485, the switching tube 591 is normally conducting if the previous alignment cycle has been completed. Accordingly, when the switch 500 is closed, the negative potential produced in the manner described above across the resistor 576 is applied to the suppressor grid of the switching tube 591 and operates to render the tube 591 non-conductive. The starting control switching circuit 590 is thus keyed to the opposite position in which the tube 592 is conducting and the tube 591 is non-conducting. When the tube 592 is conducting, the control grid potential thereof is substantially at ground potential and the control grid potential of the tube 592 is supplied through the resistor 586 to the first control grid of the starting control tube 581. Accordingly, when the switch 500 is closed and the switching tube 592 is rendered conductive, the starting control tube 581 is also rendered conductive and the 400 cycle signal supplied to the suppressor grid of the tube 581 is repeated across the anode resistor 582 and is supplied over the conductor 469 to the phase reversal

circuit 485 so as to drive the motor 495 in the direction of the peak response point of the circuit 15.

When the peak response point is reached, the differential detector and amplifier 470 produces a negative control pulse which is supplied over the conductor 471 to the suppressor grid of the switching tube 592 and operates to turn off the switching tube 592 and turn on the switching tube 591. When the tube 592 is rendered non-conductive after the peak response point is passed, the control grid potential thereof becomes highly negative and therefore the starting control tube 581, which is controlled by the switching tube 592, is also rendered non-conductive so that the 400 cycle unbalancing voltage is removed from the conductor 469 and the motor 495 is thereafter controlled by the phase reversal circuit 485 in the manner described above.

The electronic starting circuit 465 also performs the function of supplying a starting signal over the conductor 468 to the time delay safety circuit 480 at the start of the alignment cycle and of supplying a shut-off signal to the time delay safety circuit 480 over the conductor 467 if the circuit 15, which is being aligned, is correctly wired and a peak response point is reached. To accomplish this, the voltage across the resistor 576 is utilized as a starting signal and is supplied over the conductor 468 to the time delay safety circuit 480. Also, the control grid voltage of the switching tube 592 is utilized as a shut-off signal and is supplied over the conductor 467 to the time delay safety circuit 480. When the starting switch 500 is closed at the start of the alignment cycle a negative voltage is produced across the resistor 576 and a negative starting signal is supplied over the conductor 468 to the time delay safety circuit 480 to initiate the time delay thereof. If the circuit 15 is correctly wired and a peak response point is reached, the differential detector and amplifier 470 develops a negative control pulse in the manner described above which shuts off the switching tube 592 thus reducing the control grid potential of the tube 592 to a negative value so that the shut-off signal supplied over the conductor 467 to the time delay safety circuit 480 comprises a negative-going control signal coincident with the first passage of the circuit 15 through the peak response point. In this connection it will be understood that the differential detector and amplifier 470 develops successive negative control pulses each time the circuit 15 is tuned through the peak response point. However, only the first of these control pulses is operative to turn off the switching tube 592 due to the fact that once the tube 592 is rendered non-conductive, the suppressor grid thereof loses control and the succeeding negative control pulses have no effect upon the starting control switching circuit 590. Therefor, once the starting control switching circuit is reset to its initial position it remains in this position for the remainder of the alignment cycle.

Differential detector and amplifier 470

As stated generally in connection with the general description of the alternative alignment system of Fig. 18, the differential detector and amplifier 470, which is shown in detail in Fig. 24 of the drawings, performs the function of supplying a negative control pulse to the electronic starting circuit 465 and the phase reversal circuit 485 each time the peak response point of the circuit 15 is traversed. It will be recalled that after the peak response point of the circuit 15 is reached, and the memory circuit voltage is established, the output from the comparison bridge 30 becomes positive and the output from the chopping circuit 31 comprises a 400 cycle positive-going square wave having an amplitude and sense corresponding to the departure of the comparison bridge output voltage from its initial value.

The 400 cycle positive-going square wave produced by the chopping circuit 31 in the manner described above is supplied over the conductor 20 to the control grid of a cathode follower tube 600, and is repeated across the

cathode resistor 601 thereof. The positive-going square wave repeated across the resistor 601 is integrated in the network including the series resistor 602 and the condenser 603 which are connected between the cathode of the tube 600 and ground, and the integrated wave is supplied to the control grid of a differential control tube 605. The control grid of the tube 605 is directly connected to the cathode of the tube 600 through the resistor 602 and the control grid potential of the tube 605 varies directly with the voltage across the condenser 603.

When the output from the chopping circuit 31 comprises a negative-going square wave, the average potential of the integrated square wave is negative and the tube 605 remains non-conductive. However, when the polarity of the square wave from the chopping circuit 31 reverses and a positive-going square wave is produced, the integrated voltage produced across the condenser 603 increases positively to a point at which the tube 605 conducts. When the tube 605 conducts, a negative signal is produced across the anode resistor 606 of the tube 605 and is coupled through the condenser 607 to the control grid of an amplifier tube 608. The grid resistor 609 of the tube 608 is connected to the B+ supply so that the tube 608 is normally operated at zero bias and repeats the negative signal supplied thereto as a positive signal across the anode resistor 610 thereof. The positive signal produced across the resistor 610 is again amplified and inverted in the succeeding amplifier tube 612 and is repeated as a negative signal of relatively large amplitude across the anode resistor 613 of the tube 612. The negative control pulse produced in the manner described above across the resistor 613 is supplied over the conductor 471 to the electronic starting circuit 465 and the phase reversal circuit 485 to control these units in the manner heretofore described in detail.

The application of a negative control pulse to the phase reversal circuit 485 operates to reverse the motor 495 and tune the circuit 15 back to its peak response point. As the circuit 15 is tuned back to its peak response point the square wave from the chopping circuit 31 remains of the same polarity and the integrated voltage across the condenser 603 gradually falls to zero as the peak response point is reached. When the peak response point is passed a second time the square wave from the chopping circuit 31 becomes again a positive-going square wave of increasing amplitude so that the voltage across the condenser 603 again increases positively to cause conduction of the tube 605 so that a negative pulse is produced across the output resistor 613 and is supplied to the electronic starting circuit and the phase reversal circuit in the manner described above. Accordingly, as the circuit 15 is tuned back and forth through its peak response point, the differential detector and amplifier produces a negative control pulse each time the peak response point is traversed.

Time delay control circuit 480

The time delay control circuit 480, which is discussed generally in connection with the general description of the alternative system of Fig. 18, is shown in detail in Fig. 25 of the drawings, and performs the function of disabling the motor control portion of the alignment system in the event that no peak response point is reached within a predetermined time interval after the start of the alignment cycle.

Thus, referring to Fig. 25, when the starting switch 500 is closed at the start of the alignment cycle, the voltage which is produced across the resistor 576 (Fig. 23) is supplied over the conductor 468 to a time delay circuit indicated generally at 620. The time delay circuit 620 is of the type known as a Phantastron delay circuit and provides a time delay pulse a predetermined interval after a control pulse is supplied thereto. More specifically, the control signal supplied over the conductor 468 is coupled through a condenser 619 to the suppressor grid of an electron discharge tube 621. The anode of the tube 621 is directly connected to the control grid of an electron

discharge tube 622 and the cathode of the tube 622 is back-coupled through the condenser 623 to the first control grid of the tube 621.

The Phantastron time delay circuit 620 is described in detail in "Principles of Radar" (2nd ed.) by M. I. T. Radar School Staff (McGraw-Hill), pages 2-58-64, and reference may be had thereto for a detailed description thereof. However, for the purposes of the present invention it may be stated that the suppressor grid of the tube 621 controls the division of current between the anode and the screen grid. Normally the first control grid of the tube 621 is at cathode potential so that a large current flows through the cathode resistor 626 and the anode section of the tube is cut off. When the switch 500 is released a positive pulse is produced which is coupled through the condenser 619 to the suppressor grid of the tube 621 and starts the flow of anode current and the anode potential of the tube 621 decreases. The decrease in anode potential of the tube 621 is back coupled to the first control grid of the tube 621 through the tube 622 and the condenser 623 so that the potential across the cathode resistor 626 decreases. As the condenser 623 discharges the potential across the resistor 626 remains at a low value until a discharge of the condenser 626 is accompanied by a decrease in anode current at which time the tube 621 switches back to its original condition with a relatively large voltage across the resistor 626. The diode tube 627 limits the voltage to which the condenser 623 is charged between alignment cycles and the length of the time interval is controlled by the relative values of the resistors 624 and 625. There is thus produced at the end of a predetermined time delay a positive control pulse across the resistor 626 which is coupled through the condenser 628 to the control grid of a time delay gating tube 630.

The first control grid of the gating tube 630 is normally biased beyond anode current cut-off by means of the voltage divider network including the resistors 631 and 632 which are connected between the negative supply potential and ground. The suppressor grid of the gating tube 630 is controlled by the electronic starting circuit 465 and the control grid potential of the switching tube 592 in the circuit 465 is supplied over the conductor 467 and through the resistor 633 to the suppressor grid of the gating tube 630 in the time delay control circuit 480. If the suppressor grid of the gating tube 630 is at a relatively positive potential when a positive time delay control pulse is supplied to the first control grid of the tube 630 from the time delay circuit 620, the tube 630 conducts and there is produced across the anode resistor 634 thereof a negative signal which is supplied through the coupling condenser 635 to a time delay switching circuit indicated generally at 640. The switching circuit 640 is of the modified Eccles-Jordan type and in general is similar to the electronic switching circuit 37 which has been described in detail in connection with Fig. 6 of the drawings. Generally considered, the switching circuit 640 comprises a pair of electron discharge tubes 641 and 642, which are interconnected so as to be switched abruptly from a conductive to a non-conductive state in response to a control pulse supplied to the control grid of either tube. In contradistinction to the switching circuit 37, however, the tubes 641 and 642 are of the triode type and the circuit 640 responds to either positive or negative control pulses. The control grid potential of the switching tube 642 is used as a blocking signal for the A. C. amplifier 32. Thus, the control grid of the tube 642 is connected through the resistor 644 to the cathode of a diode tube 645. The anode of the tube 645 is connected over the conductor 481 to the control grid of the first amplifier tube 222 in the A. C. amplifier 32 (Fig. 10).

Considering now the manner in which the time delay control circuit 480 operates to block the motor control system if no peak response point is reached after a predetermined time delay, it will be seen from the foregoing

description of the electronic starting circuit 465 that if a peak response point is reached the differential detector and amplifier 470 supplies a negative control pulse to the switching tube 592 (Fig. 23) so that the tube 592 is rendered non-conductive and the control grid potential thereof is abruptly switched to a relatively high negative value. When the tube 592 is rendered non-conductive the suppressor grid of the time delay gating tube 630 is also made highly negative so that the gating tube 630 can not conduct for the remainder of the alignment cycle and the time delay control pulse supplied to the first control grid of the gating tube 630 after the predetermined time delay is ineffective to cause conduction of the time delay gating tube 630. It is thus seen that if a peak response point is encountered the gating tube 630 is disabled for the remainder of the alignment cycle. However, if no peak response point is reached, the switching tube 592 remains conductive and the suppressor grid of the time delay gating tube 630 is at its positive value so that after the predetermined time delay interval, the positive time delay control pulse supplied to the first control grid of the gating tube 630 passes through the tube and appears as a negative-going signal across the anode resistor 634. The control signal thus produced across the resistor 634 operates to key the time delay switching circuit 640 to a position such that the control grid of the tube 642 thereof is at a relatively large negative value. When the control grid of the tube 642 is made highly negative in the manner described above, the diode 645 conducts due to the fact that the cathode potential thereof is made more negative than the anode potential thereof and the control grid of the amplifier tube 222 (Fig. 10) is driven to a large negative potential so that the tube 222 is unable to pass a 400 cycle driving signal to the phase reversal circuit 45 and the motor control system is positively disabled.

The time delay switching circuit 640 normally operates with the tube 642 conducting so that the control grid potential of the tube 642 is positive and the diode 645 does not conduct and therefore the A. C. amplifier 32 functions in a normal manner. If the receiver being aligned is correctly wired and a peak response point is encountered, the switching tube 642 remains conducting and it is not necessary to reset the time delay switching circuit 640. However, if a particular tunable circuit is wired incorrectly, and yields no peak response point so that the switching circuit 640 is switched in the manner described above to block the A. C. amplifier 32, it is then necessary to reset the time delay switching circuit 640 before the start of the next alignment cycle. To accomplish this, there is provided a diode tube 646, the anode of which is connected to the control grid of the switching tube 641 and the cathode of which is connected through the resetting switch 647 to the negative supply potential. The resetting switch 647 is normally open so that the diode 646 is effectively out of the circuit. However, when the time delay switching circuit 640 has been keyed by means of the pulse passed by the gating tube 630, the switch 647 is then closed before the start of the next alignment cycle so that full negative supply potential is placed on the control grid of the switching tube 641. This causes the switching circuit 640 to be keyed to its original position in which the tube 642 is conductive and the diode 645 is non-conductive. The resetting switch 647 is then opened and the system is ready for alignment of successive correctly wired tunable circuits.

While the time delay control circuit has been illustrated in connection with the alternative system of Fig. 18, it will be understood that the time delay control circuit 480 may equally well be employed with the D. C. motor driving systems of Figs. 1 and 16. If the time delay control circuit 480 is employed in the system of Fig. 1, for example, the starting relay 316 (Fig. 13) may be employed to provide a starting signal for starting the time delay control circuit and a control signal indicative of

the first passage of the tunable circuit through its peak response point. In this connection it will be recalled that the starting relay 316 is energized at the start of the alignment cycle and remains energized until after the first passage through the peak response point, at which time the relay 316 is de-energized and remains de-energized throughout the remainder of the alignment cycle. Accordingly, a first set of auxiliary contacts on the relay 316 may be employed to connect a positive signal over the conductor 468 to the time delay circuit 620 in a manner similar to the signal supplied from the electronic starting circuit 465 in the system of Fig. 18. Likewise, a second set of auxiliary contacts on the relay 316 may be employed to supply a control voltage over the conductor 467 to the gating tube 630 of the time delay control circuit 480 in a manner similar to the control signal supplied over this conductor from the electronic starting circuit 465 in the system of Fig. 18. In order to provide the correct voltage for the gating tube 630 the second auxiliary set of contacts for the relay 316 should supply a relatively positive voltage over the conductor 467 during the period when the relay 316 is energized and a negative voltage over the conductor 467 when the relay 316 is de-energized.

Counter circuit 475

As discussed generally in connection with the general description of the alternative system of Fig. 18, the counter circuit 475, which is shown in detail in Fig. 26 of the drawings, performs the function of disabling the motor control system after the tunable circuit 15 has been tuned through its peak response point a predetermined number of times. It will be recalled that the phase reversal switching circuit 550 in the phase reversal circuit 485 (Fig. 21) is reversed each time the peak response point is passed by means of a negative control pulse supplied thereto from the differential detector and amplifier 470. The control grid potential of the switching tube 552 is employed as a source of counter pulses which are supplied over the conductor 486 to the counter circuit 475.

The counter circuit 475 is, in general, similar to the counter circuit which is described in detail in connection with the alignment system disclosed in my co-pending application Serial No. 157,160 (now Patent 2,584,004), which is assigned to the same assignee as the present invention, and reference may be had to this application for a detailed description thereof. However, for the purposes of the present invention, it may be stated that the counter circuit 475 comprises a triggered multivibrator 660 comprising the tubes 661 and 662, which is normally biased to an inactive state by means of a negative bias potential applied to the control grid of the tube 661, and which is keyed in response to signals applied over the conductor 468 and through the condenser 663 to the control grid of the tube 661. Accordingly, each time a pulse is supplied to the grid of the tube 661 there is produced in the anode circuit of the tube 661 a single negative multivibrator pulse which is coupled through the condenser 664 to a first counter switching circuit 665. The switching circuit 665 is of the modified Eccles-Jordan type and provides an output pulse for each two pulses supplied thereto from the multivibrator 660. The output counter pulse from the counter circuit 665 is coupled through the condenser 666 to a second counter switching circuit 667, which is also of the modified Eccles-Jordan type and supplied an output pulse for each two counter pulses supplied thereto from the switching circuit 665.

The switching circuits 665 and 667 are initially reset to the correct position at the start of the alignment cycle by means of a counter resetting signal supplied over the conductor 468 from the electronic starting circuit 465 to the cathodes of the diode tubes 668 and 669. The anode of the tube 668 is connected to the control grid of the tube 671 of the switching circuit 665 and the anode of the tube 669 is connected to the control grid of the tube 673 of the switching circuit 667. At the start of the

alignment cycle the potential on the conductor 468 becomes highly negative so that the tubes 668 and 669 conduct and render the right hand switching tubes of the switching circuits 665 and 667 non-conductive. The counter circuit 475 is thus reset to the correct position for counting a plurality of passages through the peak response point.

In order to produce a counterblocking pulse which may be applied to the A. C. amplifier 32 to disable the 10 motor driving system after a predetermined number of traversals through the peak response point, there is provided a counteroutput circuit including the crystal rectifiers 680 and 681 and the diode tube 682. The anode of the rectifier 680 is connected through the resistor 683 15 to the control grid of the switching tube 670 and the cathode of the rectifier 680 is connected through the resistor 684 to ground. The anode of the rectifier 681 is connected through the resistor 685 to the control grid of the switching tube 672 and the cathode of the rectifier 681 is connected to the ungrounded side of the resistor 684 20 and through the resistor 686 to the negative supply potential. The voltage produced across the resistor 684 is connected to the cathode of the diode tube 682 and the anode of the tube 682 is connected over the conductor 25 476 to the control grid of the amplifier tube 222 of the A. C. amplifier 32 (Fig. 10).

Considering now the manner in which the counteroutput circuit functions to disable the A. C. amplifier 32 after a predetermined number of passages through the 30 peak response point, it will be seen that for each pulse which is supplied over the conductor 486 to the multivibrator 660 there is produced in the anode circuit of the tube 661 a negative multivibrator pulse. At the start of the alignment cycle both of the tubes 670 and 672 are 35 conducting so that the control grid potentials thereof are relatively positive and the rectifiers 680 and 681 are both conducting and produce a positive flow of current through the resistor 684. The first negative multivibrator pulse triggers the switching circuit 665 so that the tube 671 is 40 conducting and the tube 670 is cut off. When the tube 670 is cut off, the control grid potential becomes highly negative so that the rectifier 680 is rendered non-conductive and the voltage drop across the resistor 684 decreases. However, the decrease in voltage across the 45 resistor 684 is not sufficient to render the diode 682 conductive and block the A. C. amplifier 32. The second negative multivibrator pulse keys the switching circuit 665 back to its original position so that the tube 670 is again conducting and a counterpulse is supplied from the switching circuit 665 to the switching circuit 667, which 50 renders the tube 672 non-conductive. Thus, upon the occurrence of the second multivibrator pulse the rectifier 680 again conducts while the rectifier 681 is rendered non-conductive. The potential across the resistor 684 55 thus remains at a reduced or midpoint value. The third negative multivibrator pulse triggers the switching circuit 665 again so that the tube 670 is cut off and both the rectifiers 680 and 681 are non-conductive. When both the rectifiers 680 and 681 are non-conductive the 60 voltage across the resistor 684 becomes more negative so that the diode 682 conducts and connects the negative voltage across the resistor 684 to the control grid of the amplifier tube 222 (Fig. 10) so that the tube 222 is blocked and the motor control system is disabled. It 65 is thus seen that the counter circuit 475 operates to disable the motor control system after the circuit 15 has been tuned a predetermined number of times through its peak response point so as to terminate the alignment cycle.

It will be understood that the counter circuit 475, which has been illustrated in connection with the alternative system of Fig. 18, may equally well be employed in the systems of Figs. 1 and 16. In the event that the counter circuit 475 is employed to terminate the alignment cycle of the system of Fig. 1 after a predetermined number

of passages through the peak response point, the contacts 310 and 311 of the differential relay 301 (Fig. 13) may be employed as a source of countersignals which may be supplied over the conductor 486 to the input of the countercircuit 475. An auxiliary set of contacts on the starting relay 316 may also be employed automatically to provide a resetting signal over the conductor 468 to the diodes 668 and 669 to reset the countercircuit 475 at the start of the alignment cycle, in a manner similar to the resetting signal supplied over the conductor 468 from the electronic starting circuit 465 in the system of Fig. 18.

While the alignment systems of Figs. 1, 16 and 18 have been described in connection with the alignment of a single tuned resonant circuit having a single resonance peak to the correct alignment frequency, it will be evident that any of these systems may be employed to tune a double tuned resonant circuit having two resonance peaks to the correct alignment frequency. To align double tuned resonant circuits it is only necessary to reverse the polarity of the detector voltage produced across the load circuit 19 and 21 and start the alignment cycle with the double tuned circuit sufficiently in alignment to be within the resonance peaks. The alignment system then tunes the circuit to the valley between the two resonance peaks in the same way that a single tuned resonant circuit is tuned to its single resonance peak.

While particular embodiments of the invention have been shown, it will be understood, of course, that the invention is not limited thereto since many modifications may be made and it is therefore contemplated by the appended claims to cover any such modifications as fall within the true spirit and scope of the invention.

What is claimed as new and desired to be secured by Letters Patent is:

1. An automatic alignment system for aligning a tunable circuit to a predetermined frequency, comprising means for energizing said circuit at said predetermined frequency only, reversible motor means, tuning means controlled by said motor means for varying the tuning of said circuit, means for energizing said motor means to move said tuning means in a given direction, means for deriving from said circuit a sustained reference voltage representative of the response of said circuit at said predetermined frequency, means for deriving a control voltage equal to the difference between said reference voltage and the instantaneous voltage across said circuit, means for reversing said motor means in response to the tuning of said circuit through the point of peaked response, and means for controlling said motor means after reversal thereof in accordance with said control voltage, thereby to tune said circuit to said predetermined frequency.

2. An automatic alignment system for aligning a tunable circuit to a predetermined frequency, comprising means for energizing said circuit at said predetermined frequency only, reversible motor means, tuning means controlled by said motor means for varying the tuning of said circuit, means for energizing said motor means to move said tuning means in a given direction, means for deriving from said circuit a sustained reference voltage representative of the response of said circuit at said predetermined frequency, means for deriving a control voltage equal to the difference between said reference voltage and the instantaneous voltage across said circuit, means for reversing said motor means when said control voltage is of predetermined magnitude, and means for controlling said motor means after reversal thereof in accordance with said control voltage, thereby to tune said circuit to said predetermined frequency.

3. An automatic alignment system for aligning a tunable circuit to a predetermined frequency, comprising means for energizing said circuit at said predetermined frequency, reversible motor means, tuning means controlled by said motor means for varying the tuning of said circuit, means for energizing said motor means to move

said tuning means in a given direction, means for deriving from said circuit a sustained reference voltage representative of the peak response of said circuit, means for deriving a control voltage equal to the difference between said reference voltage and the instantaneous voltage across said circuit, means for reversing said motor means after the peak response point of said circuit is passed, means for controlling said motor means after reversal thereof in accordance with said control voltage thereby to tune said circuit to the peak response point thereof, and means for successively reversing the polarity of said control voltage each time said circuit is tuned through the peak response point thereof.

4. In an automatic alignment system for aligning a tunable circuit to a predetermined frequency, comprising means for energizing said circuit at said predetermined frequency, reversible motor means, tuning means controlled by said motor means for varying the tuning of said circuit, means for deriving from said circuit a sustained reference voltage representative of the response of said circuit at said predetermined frequency, means for obtaining a control voltage equal to the difference between said reference voltage and the instantaneous voltage across said circuit, means for controlling said motor means in accordance with said control voltage, thereby to tune said circuit to said predetermined frequency, and means for de-energizing said motor means after a predetermined time interval if no peak response point is reached.

5. An automatic alignment system for aligning a tunable circuit to a predetermined frequency, comprising means for energizing said circuit at said predetermined frequency, reversible motor means, tuning means controlled by said motor means for varying the tuning of said circuit, means for energizing said motor means to move said tuning means in a given direction, means for deriving from said circuit a sustained reference voltage representative of the peak response of said circuit, means for deriving a control voltage equal to the difference between said reference voltage and the instantaneous voltage across said circuit, means for reversing said motor means after the peak response point of said circuit is passed, means for controlling said motor means after reversal thereof in accordance with said control voltage thereby to tune said circuit to the peak response point thereof, means for successively reversing the polarity of said control voltage each time said circuit is tuned through the peak response point thereof, and means for de-energizing said motor means after a predetermined number of reversals of the polarity of said control voltage.

6. In an automatic alignment system for aligning a tunable circuit to a predetermined frequency, a memory circuit, comprising, means for energizing said tunable circuit at said predetermined frequency, a storage condenser, means for tuning said tunable circuit toward the peak response point thereof, means for deriving from said tunable circuit a voltage proportional to the instantaneous response thereof, and means for charging said condenser during periods when said instantaneous response voltage is increasing in magnitude.

7. In an automatic alignment system for aligning a tunable circuit to a predetermined frequency, a memory circuit comprising, means for energizing said tunable circuit at said predetermined frequency, a storage condenser, means for tuning said tunable circuit toward the peak response point thereof, means for deriving from said tunable circuit a voltage proportional to the instantaneous response thereof, and means for increasing the charge on said condenser only during periods when said derived voltage is greater than the voltage across said condenser.

8. In an automatic alignment system for aligning a tunable circuit to a predetermined frequency, a memory circuit comprising, means for energizing said tunable circuit at said predetermined frequency, a storage condenser

ser, means for tuning said tunable circuit toward the peak response point thereof, means for driving from said tunable circuit a voltage proportional to the instantaneous response thereof, means for deriving a control voltage equal to the difference between said derived voltage and the voltage across said condenser, and means for increasing the charge on said condenser when said control voltage is of a given polarity.

9. In an automatic alignment system for aligning a tunable circuit to a predetermined frequency, a memory circuit comprising, means for energizing said tunable circuit at said predetermined frequency, a storage condenser, means for tuning said tunable circuit toward the peak response point thereof, means for deriving from said tunable circuit a voltage proportional to the instantaneous response thereof, means for deriving a control voltage equal to the difference between said derived voltage and the voltage across said condenser, means for converting said control voltage into a square wave of corresponding amplitude and sense, and means for increasing the charge on said condenser when said square wave is of a given polarity.

10. In an automatic alignment system for aligning a tunable circuit to a predetermined frequency, a memory circuit comprising, means for energizing said tunable circuit at said predetermined frequency, a storage condenser, means for tuning said tunable circuit toward the peak response point thereof, means for deriving from said tunable circuit a voltage proportional to the instantaneous response thereof, means for deriving a control voltage equal to the difference between said derived voltage and the voltage across said condenser, means for converting said control voltage into a square wave of corresponding amplitude and sense, means for increasing the charge on said condenser during predetermined portions of said square wave and then only during periods when said square wave is of a given polarity.

11. In an automatic alignment system for aligning a tunable circuit to a predetermined frequency, a memory circuit comprising, means for energizing said tunable circuit at said predetermined frequency, a storage condenser, means for tuning said tunable circuit toward the peak response point thereof, means for deriving from said tunable circuit a voltage proportional to the instantaneous response thereof, means for deriving a control voltage equal to the difference between said derived voltage and the voltage across said condenser, means for converting said control voltage into a square wave of corresponding amplitude and sense, and means for charging said condenser from an independent voltage source, said last-named means being started when said square wave is of a given polarity and terminated when said derived voltage and the voltage across said condenser are equal.

12. In an automatic alignment system for aligning a tunable circuit to a predetermined frequency, the combination of means for deriving from said circuit a voltage representative of the instantaneous response thereof, a storage condenser, means for comparing said instantaneous response voltage and the voltage across said condenser to obtain a voltage equal to the difference therebetween, an oscillator, means controlled by said oscillator for converting said difference voltage into control pulses of the same amplitude and sense, a square wave generator controlled by said oscillator, gating means controlled by said square wave generator for selecting those pulses which occur during periods when said response voltage is greater than said condenser voltage, and means for charging said condenser in accordance with said selected pulses, thereby to provide across said condenser a reference voltage indicative of the maximum response of said circuit.

13. In an automatic alignment system for aligning a tunable circuit to a predetermined frequency, the combination of means for deriving from said circuit a voltage representative of the instantaneous response thereof,

a storage condenser, means for comparing said instantaneous response voltage and the voltage across said condenser to obtain a voltage equal to the difference therebetween, an oscillator, means controlled by said oscillator for converting said difference voltage into control pulses of the same amplitude and sense, a square wave generator controlled by said oscillator, gating means controlled by said square wave generator for selecting those pulses which occur during periods when said response voltage is greater than said condenser voltage, and means for charging said condenser for the duration of each of said selected pulses, thereby to provide across said condenser a reference voltage indicative of the maximum response of said circuit.

14. An automatic alignment system for aligning a tunable circuit to a predetermined frequency comprising, means for deriving from said circuit a voltage representative of the instantaneous response thereof, a storage condenser, means for charging said condenser, means for comparing said instantaneous response voltage and the voltage across said condenser to obtain a voltage equal to the difference between said two voltages, an oscillator, a square wave generator controlled by said oscillator, means for energizing said charging means only during periods when said difference voltage is of a given polarity, means controlled by said oscillator for converting said difference voltage into an intermediate square wave of the same amplitude and sense as said difference voltage, means for amplifying said intermediate square wave, means for converting said square wave into a pair of unidirectional voltages which are balanced with respect to a predetermined reference potential, and means for controlling the tuning of said circuit in accordance with said pair of uni-directional voltages.

15. In an automatic alignment system for aligning a tunable circuit to a predetermined frequency, the combination of means for deriving from said circuit a voltage representative of the instantaneous response thereof, a storage condenser, means for comparing said instantaneous response voltage and the voltage across said condenser to obtain a difference voltage, means for charging said condenser only when said difference voltage is of given polarity, a source of oscillations, means controlled by said oscillation source for converting said difference voltage into an intermediate square wave of the same amplitude and sense as said difference voltage, means for amplifying said intermediate square wave, means for deriving from said intermediate square wave a pair of continuous output voltages which are balanced with respect to a predetermined reference potential, and means for controlling the tuning of said circuit in accordance with said continuous output voltages when said difference voltage is of the opposite polarity.

16. In an automatic alignment system for aligning a tunable circuit to a predetermined frequency, the combination of means for deriving from said circuit a voltage representative of the instantaneous response thereof, a storage condenser means for comparing said instantaneous response voltage and the voltage across said condenser to obtain a difference voltage, means for charging said condenser only when said difference voltage is of a given polarity, a source of oscillations, means controlled by said oscillation source for converting said difference voltage into an intermediate square wave of the same amplitude and sense as said difference voltage, means for amplifying said intermediate square wave, means controlled by said source of oscillations for deriving from said intermediate square wave a pair of unidirectional control voltages which vary in opposite directions from a predetermined reference level in accordance with variations in the amplitude and sense of said different voltage, and means for controlling the tuning of said circuit in accordance with said control voltages when said difference voltage is of the opposite polarity.

17. In an automatic alignment system, means for

amplifying a continuous input voltage which varies gradually over a predetermined range of values on either side of an initial value comprising, means for obtaining a continuous control voltage having an amplitude and sense representative of the departure of said continuous input voltage from its initial value, an oscillator, a square wave generator controlled by said oscillator, means controlled by said oscillator for converting said control voltage into an intermediate square wave of corresponding amplitude and sense, means for amplifying said intermediate square wave, and means controlled by said square wave generator for deriving from said intermediate square wave a pair of continuous output voltages which are balanced with respect to a predetermined reference potential and which vary in amplitude and sense in accordance with the departure of said continuous input voltage from said initial value.

18. In an automatic alignment system, means for amplifying a continuous input voltage which varies gradually over a predetermined range of values on either side of an initial value comprising, means for obtaining a continuous control voltage having an amplitude and sense representative of the departure of said continuous input voltage from its initial value, a source of oscillations, chopping means controlled by said oscillation source for converting said control voltage into an intermediate square wave having the same amplitude and sense as said control voltage, means for amplifying said intermediate square wave, and gating means controlled by said oscillation source for deriving from said intermediate square wave a pair of continuous output voltages which are balanced with respect to a predetermined reference potential and which vary in amplitude and sense in accordance with the departure of said continuous input voltage from said initial value.

19. In an automatic alignment system, means for amplifying a continuous input voltage which varies gradually over a predetermined range of values on either side of an initial value comprising, means for obtaining a continuous control voltage having an amplitude and sense representative of the departure of said continuous input voltage from its initial value, a source of oscillations, chopping means controlled by said oscillation source for converting said control voltage into an intermediate square wave having the same amplitude and sense as said control voltage, means for amplifying said intermediate square wave, and gating means controlled by said oscillation source for deriving from said intermediate square wave a pair of continuous output voltages which are balanced with respect to a predetermined reference potential and which vary in amplitude and sense in accordance with the departure of said continuous input voltage from said initial value, said last named means including a pair of electron discharge devices, means for rendering said devices alternately conductive in accordance with the output from said oscillation source, means for applying said intermediate square wave in like phase to both of said devices, and means for integrating the composite square waves produced in the anode circuits of said devices thereby to provide said pair of continuous output voltages.

20. In an automatic alignment system, means for amplifying a continuous input voltage which varies gradually over a predetermined range of values on either side of an initial value comprising, means for obtaining a continuous control voltage having an amplitude and sense representative of the departure of said input voltage from its initial value, an oscillator, a square wave generator controlled by said oscillator, means controlled by said oscillator for converting said control voltage into an intermediate square wave having the same amplitude and sense as said control voltage, means for amplifying said intermediate square wave, a pair of electron discharge devices, means for applying a control square wave of a given polarity from said generator

to one of said devices, means for applying a control square wave of the opposite polarity from said generator to the other of said devices, means for applying said amplified intermediate square wave to both of said devices in the same phase, and means for deriving from said devices a pair of continuous output voltages which are balanced with respect to a predetermined reference potential and which vary in amplitude and sense in accordance with the departure of said continuous input voltage from said initial value.

21. In an automatic alignment system, means for amplifying a continuous input voltage which varies gradually over a predetermined range of values on either side of an initial value comprising, means for obtaining a continuous control voltage having an amplitude and sense representative of the departure of said input voltage from its initial value, a source of oscillations, means controlled by said oscillation source for converting said controlled voltage into an intermediate square wave having the same amplitude and sense as said control voltage, means for amplifying said intermediate square wave, means for combining said amplified intermediate square wave with a first control square wave derived from said oscillation source and of a given polarity to provide a first continuous output voltage, and means for combining said amplified intermediate square wave with a second control square wave derived from said oscillation source and of the opposite polarity to provide a second continuous output voltage, said output voltages being balanced with respect to a predetermined reference potential and variable in amplitude and sense in accordance with the departure of continuous input voltage from said initial value.

22. An automatic alignment system for aligning a tunable circuit to a predetermined center frequency comprising, reversible motor means for varying the tuning of said circuit and adapted to be energized from a power source of predetermined power frequency, means for deriving from said circuit an error signal indicative of the amount said circuit is mistuned from said center frequency, means for converting said error signal into an alternating current wave of said power frequency and of an amplitude and sense corresponding to said error signal, means including an amplifying channel for supplying said alternating current wave to said motor means, means for initially introducing a control signal of said power frequency and of predetermined phase into said channel to cause said motor means to tune said circuit through said center frequency and for thereafter removing said control signal from said channel, means for reversing the phase of said alternating current wave each time said circuit is tuned beyond said center frequency, said last-named means including an electronic switching circuit, and means responsive to passage of said circuit through said center frequency for keying said switching circuit thereby selectively to supply oppositely phased alternating current waves to said motor means.

23. An automatic alignment system for aligning a tunable circuit to a predetermined center frequency comprising, reversible motor means for varying the tuning of said circuit and adapted to be energized from a power source of predetermined power frequency, means for deriving from said circuit an error signal indicative of the amount said circuit is mistuned from said center frequency, means for converting said error signal into an alternating current wave of said power frequency and of an amplitude and sense corresponding to said error signal, means including an amplifying channel for supplying said alternating current wave to said motor means, means for initially introducing a control signal of said power frequency and of predetermined phase into said channel to cause said motor means to tune said circuit through said center frequency and for thereafter removing said control signal from said channel, and means for reversing the phase of said alternating current wave each

time said circuit is tuned beyond said center frequency, said last-named means including means for deriving signals of opposite phase from said channel, an electronic switching circuit, and means responsive to passage of said circuit through said center frequency for keying said switching circuit, thereby selectively to supply one or the other of said oppositely phased signals to said motor means.

24. An automatic alignment system for aligning a tunable circuit to a predetermined center frequency comprising, reversible motor means for varying the tuning of said circuit and adapted to be energized from a power source of predetermined power frequency, means for deriving from said circuit an error signal indicative of the amount said circuit is mistuned from said center frequency, means for converting said error signal into an alternating current wave of said power frequency and of an amplitude and sense corresponding to said error signal, means including an amplifying channel for supplying said alternating current wave to said motor means, means for initially introducing a control signal of said power frequency and of predetermined phase into said channel to cause said motor means to tune said circuit through said center frequency and for thereafter removing said control signal from said channel, means for reversing the phase of said alternating current wave each time said circuit is tuned beyond said center frequency, and means controlled by said last-named means for stopping said motor means after said circuit has been tuned through said center frequency a predetermined number of times.

25. An automatic alignment system for aligning a tunable circuit to a predetermined center frequency, comprising reversible motor means for varying the tuning of said circuit and adapted to be energized from a power source of predetermined power frequency, means for deriving from said circuit an error signal of a frequency equal to said power frequency and having an amplitude proportional to the mistuning of said circuit from said center frequency, means for deriving signals of opposite phase from said error signal, means for sequentially selecting one of said oppositely phased signals each time said circuit is tuned beyond said center frequency, means responsive to the selected one of said oppositely phased signals for controlling said motor means, and means controlled by said sequential selecting means for stopping said motor means after said circuit has been tuned through said center frequency a predetermined number of times.

26. An automatic alignment system for aligning a tunable circuit to a predetermined center frequency, comprising reversible motor means for varying the tuning of said circuit and adapted to be energized from a power source of predetermined power frequency, means for deriving from said circuit an error signal of a frequency equal to said power frequency and having an amplitude proportional to the mistuning of said circuit from said center frequency, means for deriving signals of opposite phase from said error signal, an output circuit arranged to control said motor means in accordance with signals impressed thereon, means for sequentially impressing upon said output circuit one of said oppositely phased signals each time said circuit is tuned beyond said center frequency, and means for initially impressing upon said output circuit a starting signal of predetermined phase to cause said motor means initially to tune said circuit through said center frequency and for thereafter removing said starting signal from said output circuit.

27. An automatic alignment system for aligning a tunable circuit to a predetermined center frequency, comprising reversible motor means for varying the tuning of said circuit and adapted to be energized from a power source of predetermined power frequency, means for deriving from said circuit an error signal of a frequency equal to said power frequency and having an amplitude proportional to the mistuning of said circuit from said center frequency, means including a pair of phase in-

verters for deriving two pairs of signals of opposite phase from said error signal, a pair of balanced output stages arranged to control said motor means in accordance with signals impressed thereon, means for impressing one signal from each of said pairs on each of said output stages, and means including an electronic switching circuit and responsive to each tuning of said circuit through said center frequency for sequentially controlling said phase inverters, thereby to reverse said motor means each time said circuit is tuned through said center frequency.

28. An automatic alignment system for aligning a tunable circuit to a predetermined center frequency comprising, reversible motor means for varying the tuning of said circuit and adapted to be energized from a power source of predetermined power frequency, means for deriving from said circuit an error signal of a frequency equal to said power frequency and having amplitude proportional to the mistuning of said circuit from said center frequency, means including a pair of phase inverters for deriving two pairs of signals of opposite phase from said error signal, a pair of balanced output stages arranged to control said motor means in accordance with signals impressed thereon, means for impressing one signal from each of said pairs on each of said output stages, means including an electronic switching circuit and responsive to each tuning of said circuit through said center frequency for sequentially controlling said phase inverters, thereby to reverse said motor means each time said circuit is tuned through said center frequency, and means controlled by said electronic switching circuit for stopping said motor means after said circuit has been tuned through said center frequency a predetermined number of times.

29. An automatic alignment system for aligning a tunable circuit to a predetermined center frequency comprising, reversible motor means for varying the tuning of said circuit and adapted to be energized from a power source of predetermined power frequency, means for deriving from said circuit an error signal of a frequency equal to said power frequency and having an amplitude proportional to the mistuning of said circuit from said center frequency, means including a pair of phase inverters for deriving two pairs of signals of opposite phase from said error signal, a pair of balanced output stages arranged to control said motor means in accordance with signals impressed thereon, means for impressing one signal from each of said pairs on each of said output stages, means including an electronic switching circuit and responsive to each tuning of said circuit through said center frequency for sequentially controlling said phase inverters, thereby to reverse said motor means each time said circuit is tuned through said center frequency, and means for initially impressing upon one of said output stages a starting signal of predetermined phase to cause said motor means initially to tune said circuit through said center frequency and for thereafter removing said starting signal from said one output stage.

30. In an automatic alignment system for aligning a tunable circuit to a predetermined center frequency, the combination of, tuning means for varying the tuning of said circuit, a starting switch, means responsive to closure of said starting switch for moving said tuning means in the direction to tune said tunable circuit to said center frequency, means responsive to closure of said starting switch for stopping said tuning means after a predetermined time delay, and means responsive to tuning of said tuning of said tunable circuit through said center frequency for rendering said last-named means ineffective.

31. In an automatic alignment system for aligning a tunable circuit to a predetermined center frequency, the combination of, tuning means for varying the tuning of said circuit, a starting switch, means responsive to closure of said starting switch for moving said tuning means in the direction to tune said tunable circuit to said center frequency, a time delay circuit adapted to stop said tuning means a predetermined interval after closure of said start-

ing switch, and means responsive to tuning of said tunable circuit through said center frequency for disabling said time delay circuit.

32. An automatic alignment system for aligning a tunable circuit to a predetermined center frequency comprising, tuning means for varying the tuning of said circuit, means for deriving from said circuit an error signal having an amplitude proportional to the mistuning of said circuit from said center frequency, means for initially controlling said tuning means to tune said circuit through said center frequency and for thereafter controlling said tuning means in accordance with said error signal, means for developing control pulses each time said circuit is tuned through said center frequency, a time delay circuit for stopping said tuning means a predetermined interval after initial starting thereof, means responsive only to the first of said control pulses for disabling said time delay circuit, and means for reversing the phase of said error signal in response to each of said control pulses.

33. An automatic alignment system for aligning a tunable circuit to a predetermined center frequency comprising, tuning means for varying the tuning of said circuit, means for deriving from said circuit an error signal having an amplitude proportional to the mistuning of said circuit from said center frequency, means for initially controlling said tuning means to tune said circuit through

said center frequency and for thereafter controlling said tuning means in accordance with said error signal, means for developing control pulses each time said circuit is tuned through said center frequency, a time delay circuit for stopping said tuning means a predetermined interval after initial starting thereof, means responsive only to the first of said control pulses for disabling said time delay circuit, means for reversing the phase of said error signal in response to each of said control pulses, and means responsive to a predetermined number of said control pulses for stopping said tuning means.
